**MACHINE AND METHOD FOR COVERING
TRAYS AND THE LIKE**

William E. Cheeley, Chesterfield County, and Jens R. L. Moller, and Vincent J. Serio, Jr., Henrico County, Va., assignors to Reynolds Metal Company, Richmond, Va., a corporation of Delaware

Filed Dec. 20, 1961, Ser. No. 160,771
41 Claims. (Cl. 53—38)

This invention relates to a machine and method for placing and wrapping sheet covers over the edges of trays.

The invention is applicable to the covering of relatively shallow, substantially rectangular trays or receptacles, such as at present known as frozen dinner trays. However, the invention is applicable to many other types of trays or receptacles.

The invention lends itself to high quantity and high quality production of covered trays or receptacles. The trays, with food or the like in them, may be placed on a feed belt construction. Thereafter, the trays are automatically advanced, have sheet covers placed over them, and have the covers effectively wrapped around the edges of the trays. These operations are performed quickly and in high quantity so the food may be quickly frozen and preserved in the trays.

For example, a machine is provided in which, for example, dinner trays, with prepared food or the like in them, are placed on an automatic tray feeding, arresting and releasing construction. The trays are then automatically fed along the machine at proper intervals so the trays are automatically placed in openings of a traveling belt or conveyor. Covers are automatically cut from strip material and are placed over the trays. The covers and trays are carried forward under a tray and cover securing mechanism. The covers and trays are then lifted from the traveling belt or conveyor into the tray and cover securing units.

The trays and covers continue to travel forward within tray and cover securing units within which the covers are wrapped around or secured to the edges of the trays. Thereafter, the wrapped covers and trays are removed from the securing units and are placed on delivering devices which carry the covered trays to any desired place, such as adjacent to freezing compartments and the like.

The operation is substantially automatic once the filled trays are placed on the tray feeding construction.

Automatic stopping controls may be provided to stop operation of the machine if there is a failure to provide a tray at the proper time in an opening of the traveling conveyor.

Also, automatic controls may be provided for stopping the machine if there is a failure to provide a cover for a filled tray.

The trays and covers may travel along in a horizontal plane for a substantial distance within the cover securing units, so there is ample time for the cover wrapping operation to be performed before the covered trays are separated from the cover securing units.

The covers are efficiently wrapped at the corners of the tray and then along the sides of the tray to produce a relatively tight wrap of the cover.

The operations are performed smoothly on continuously moving orbital conveyors of strong construction.

Accordingly, it is among the objects of this invention to provide an apparatus and a method having one or more of the features herein disclosed.

Other objects are apparent from this description and/or the accompanying drawings, in which:

FIGURE 1 is a diagrammatic side elevation of the first half (more or less) of the machine.

2

FIGURE 2 is a diagrammatic plane view of FIGURE 1, with upper parts omitted.

FIGURE 3 is a diagrammatic side elevation of the second half (more or less) of the machine.

5 FIGURE 4 is a diagrammatic plan view of FIGURE 3, with upper parts omitted.

FIGURE 5 is a diagrammatic and composite cross section taken generally along the line 5—5 of FIGURE 3.

10 FIGURE 6 is a diagrammatic side view, on enlarged scale, of a portion of the left end of FIGURE 1.

FIGURE 6A is a top view of a portion of FIGURE 7 on enlarged scale, and showing certain additional details.

FIGURE 6B is a cross section along line 6B—6B of FIGURE 6A.

15 FIGURE 7 is a diagrammatic plan view of FIGURE 6.

FIGURE 8 is a diagrammatic cross section along line 8—8 of FIGURE 7.

FIGURE 8A is a diagrammatic cross section along arrows and line 8A of FIGURE 6.

20 FIGURE 9 is a diagrammatic side view of a right end continuation of FIGURE 7 and showing the transfer of trays from the stationary bar supports to the moving belt.

FIGURE 10 is a diagrammatic plan view of FIGURE 9.

FIGURE 11 is a generally longitudinal cross section 25 taken rearward of a portion of FIGURE 9, and showing the tray lowering mechanism.

FIGURE 12 is an enlarged cross section taken along the line 12—12 of FIGURE 11.

FIGURE 13 is a generally longitudinal elevation and cross section in the same general location of FIGURES 9 and 11 showing the mechanism for sensing the absence of a tray on the moving tray belt.

FIGURE 13A shows the actuating lever of FIGURE 13 in full lines and some of the other parts in dotted lines, so the shape of the actuating lever becomes apparent.

FIGURE 14 is an enlarged cross section along line 14—14 of FIGURE 13.

FIGURE 15 is a top plan view of the cover feed assembly.

40 FIGURE 16 is a side view taken from line 16—16 of FIGURE 15.

FIGURE 17 is a cross section along line 17—17 of FIGURE 16.

45 FIGURE 18 is a diagrammatic top view of the cover longitudinal conveying system.

FIGURE 19 is a side view taken along the line 19—19 of FIGURE 18.

FIGURE 20 is a side elevation of the sealing unit carrying mechanism with the sealing unit.

50 FIGURE 21 is a diagrammatic view of the left end of FIGURE 48 with the sealing unit located midway down between the upper and lower horizontal runs.

FIGURE 22 is a top plan view of FIGURE 20.

FIGURE 23 is a vertical cross section of a tray lifter.

FIGURE 24 is a top plan view of the sealing unit on enlarged scale, with the right half in open position and with the left half in crimping position.

55 FIGURE 25 is a cross section along line 25—25 of FIGURE 24, also with the right half in open position and with the left half in crimping position.

FIGURE 26 is an enlarged cross section along line 26—26 of FIGURE 24.

FIGURE 27 is an enlarged cross section along line 27—27 of FIGURE 24.

60 FIGURE 28 is a cross section along line 28—28 of FIGURE 24.

FIGURE 29 is a side elevation of the tray discharge conveyor construction.

65 FIGURE 30 is a plan view of FIGURE 29.

FIGURE 31 is an enlarged cross section along line 31 of FIGURE 29.

FIGURE 32 is a top view of the tray supporting track of FIGURES 29-31.

FIGURE 33 shows a side view of a type of tray and cover adapted to be carried together and united according to this invention.

FIGURE 34 shows a plan view of the tray of FIGURE 33 with the cover shown in dotted lines.

FIGURE 35 is a longitudinal diagrammatic cross section showing the trays 12 and covers 10 being moved toward the sealing unit.

FIGURE 36 is a diagrammatic cross section with parts broken away or omitted and taken along the line 36-36 of FIGURE 14 and with the tray shown in dotted lines and showing the tray-supporting plates and their attachment to the supporting chain belt.

FIGURE 37 is a diagrammatic top view of one of the pairs of the tray-supporting plates of FIGURE 14 in reduced scale.

FIGURE 38 is a perspective, partly in cross section, of the cover feeding trough and cover arresting and releasing gate.

FIGURE 39 is a cross section along line 39-39 of FIGURE 38.

FIGURE 40 is a cross section along line 40-40 of FIGURE 38, with the slight curvature of the parts disregarded.

FIGURE 41 is a cross section along line 41-41 of FIGURE 38.

FIGURE 42 is a schematic wiring diagram for the cover absence sensing mechanism.

FIGURE 43 is an enlarged plan view of the finger opening cam at the lower right hand corner of FIGURE 18.

FIGURE 44 is a vertical cross section along line 44-44 of FIGURE 43.

FIGURE 45 is an enlarged top view of certain parts of the lower right hand corner of FIGURE 24, with the main plate shown in dotted lines.

FIGURE 46 is a corner side view of FIGURE 45 taken from the line 46-46 of FIGURE 45.

FIGURE 47 is a plan view of the corner wrapping plate which is shown in FIGURES 45 and 46.

FIGURE 48 is a view somewhat similar to FIGURE 20 showing mainly the course of travel of the sealing units, trays and covers.

FIGURE 49 is a diagrammatic top plan view partly in cross section along line 49-49 of FIGURE 50 of one of the sealing units as supported by the chain conveyors, and with one end of the sealing unit firmly held in level position by a pair of auxiliary cog wheels or star wheels.

FIGURE 50 is a diagrammatic phantom side view of a portion of FIGURE 49.

FIGURE 51 is a partial vertical elevation taken along the line 51-51 of FIGURE 45.

FIGURE 52 is a diagrammatic cross section along line 52-52 of FIGURE 21.

FIGURE 53 is a diagrammatic vertical cross section along the line 53-53 of FIGURE 49 with the tray and cover securing unit in the midway downward position.

FIGURE 54 is a view similar to FIGURE 53 but showing another embodiment.

FIGURE 55 is a diagrammatic plan view showing the belt drives, the shafts and some gears of the apparatus.

FIGURE 56 is a diagrammatic side view showing substantially the same elements of FIGURE 55 in side elevation.

This invention relates to a machine and method for placing and wrapping sheet covers, such as shown at 10, FIGURES 33 and 34, over the edges of trays or receptacles, such as tray or receptacle 12. The trays and covers may be made of aluminum containing metallic material, such as commercially pure aluminum and/or suitable aluminum alloys in sheet form, and may be of the type now marketed for "dinner trays" and the like.

The trays may have top outward tray rims 14, inward tray bottoms 16, and upward tray sides 18. If desired,

they may have an edge bead 22, and bottom dividing walls or ridges 24. Such trays are now well known and are on the market.

For convenience in description, certain directional adjectives or other words are used, such as upward, downward, rightward, leftward, etc. However, it is to be understood that the parts or actions so described may be used in different directions, and that the position of the viewing person alters the description.

FIGURES 1 and 3 are diagrammatic side elevations of the machine and indicate respectively by brackets F6, F9, F11, F13, F19, F20, and F29 where the side views in FIGURES 6, 9, 11, 13, 19, 20, and 29 are located in the machine with reference to FIGURES 1 and 3.

Some of the main features of this invention are briefly outlined in the following paragraphs. A more detailed description thereof follows.

An automatic tray or receptacle feeding, tray arresting and regulated tray releasing belt construction 26 may be provided, such as shown in FIGURES 6, 6A, 6B, 7, 8, and 8A, which may be located in the zone of bracket F6 of FIGURE 1.

A stationary tray or receptacle feeding track construction 28, 29, FIGURES 1, 6-8, 8A, 10-12, receives and supports the inward bottoms 16 of the trays 12 which are released by the tray releasing belt construction 26.

A tray or receptacle pushing mechanism or belt 30, FIGURES 1, 6, 7, and 9 is provided for pushing the trays 12 along the feeding track construction 28, 29, etc.

A tray or receptacle lowering construction 32, FIGURES 1, 11, and 12, receives trays 12 from said tray feeding track construction 28, 29 at one level 34 and lowers said trays to a lower level 36 and automatically feeds them into the tray openings 134 of an orbital conveyor 38.

A tray or receptacle supporting orbital conveyor 38, FIGURES 1-4, etc., for supporting and transporting a series of trays 12 longitudinally along the conveyor receives and transports the lowered trays 12 from the tray lowering construction 32 in suitable tray openings 134.

A tray or receptacle absence sensing means 40, 42, etc., FIGURES 1 and 13, controls the machine in response to the accidental absence of a tray 12 from an opening of the orbital conveyor 38 where such tray 12 should otherwise be.

A sheet cover feeding means 44, FIGURES 1, 15-18 and 38-41 is provided for automatically feeding sheet covers 10, FIGURES 33 and 34, at the rate of one cover 10 for each tray or receptacle 12 which is carried by said orbital conveyor 38. The feeding means may be supported on frame 45.

Sheet cover moving means 46, FIGURES 15-19, 43 and 44 are provided for moving said sheet covers 10 over and along with each respective tray or receptacle 12 from said sheet cover feeding means 44 to a cover and tray securing mechanism 48, FIGURES 1, 5, 20-28.

A cover absence sensing mechanism 50, FIGURE 42, etc., is provided for controlling said machine in response to the accidental absence of a cover in said sheet cover moving means 46.

The cover and tray or receptacle securing mechanism 48 is placed above a portion of the orbital conveyor 38.

A tray or receptacle and cover raising and lowering mechanism 52, FIGURES 5 and 23, is provided for raising said trays 12 and covers 10 from said orbital conveyor 38 to said cover and tray securing mechanism 48 and then lowering said trays and covers.

Means 54 are provided to operate said cover and tray or receptacle securing mechanism 48 while said covers 10 and trays 12 are raised.

A stationary tray or receptacle and cover receiving track construction 56, FIGURES 1, 29-32, is provided for receiving and supporting said trays 12 and covers 10 from said tray and cover raising and lowering mechanism 52.

A tray or receptacle and cover pushing mechanism 58 is provided for pushing said trays 12 and covers 10 along said tray and cover receiving track construction 58.

If desired, a tray or receptacle and cover receiving and discharging belt construction 60 may be provided for receiving said trays 12 and covers 10 from said stationary tray and cover receiving track construction 56 for delivery away from said machine.

The above members designated by certain reference numerals between 10 and 60 inclusive, are additionally elsewhere more fully described.

The words "tray" and "receptacle" as herein used are intended to be interchangeable and to include receptacles of various kinds, which have the general characteristics of the receptacle or tray 12 herein disclosed.

Certain orbital conveyors, chains, or belts herein disclosed, such as 26, 30, 38, etc., have pulley constructions which rotate about horizontal axes, which cause the entire conveyor to have a horizontal rotational axis, which term is herein used at times to identify this type of rotation. Other orbital conveyors, chains, or belts, such as conveyors or chains 297 of the sheet moving means 46, have pulley or sprocket wheel constructions which rotate about vertical axes, which cause the entire conveyor to have a vertical rotational axis, which term is herein used at times to identify this type of rotation. It is to be understood that terms of this character can be applied at any time to the various conveyors as illustrated for the sake of brevity and clearness without further explanation.

Alternatively, conveyors such as 26, 30, 38, etc., may be conveniently identified by words such as "vertical orbital conveyors" to describe the general plane in which they travel. Also, conveyors such as conveyors 297 may be conveniently similarly identified by such words as "horizontal orbital conveyors."

The automatic feeding and releasing belt construction 26

The automatic tray or receptacle feeding, arresting, and regulated releasing belt construction 26 is shown in FIGURES 1, 6, 6A, 6B, 7, 8, and 8A. It is located in a zone indicated by the bracket F6 in FIGURE 1.

This construction 26 may include a pair of friction belts or friction means 62 which are supported tightly by pairs of pulleys 64 and 66 which are mounted on shafts 65 and 67 respectively to produce horizontal upper runs. A pair of side angle beams 68 are supported by brackets 70 from the side plate beams 72.

The belts 62 may be maintained in a substantially straight span condition by any suitable construction, such as by the horizontal plate construction 74 which is supported by pins 76 and horizontal flat bars 78 which are carried by brackets 80 on beams 70.

Additionally or alternatively, the upper runs of the belts 62 may be supported on the idler pulleys 69 which may support the under side of the belts 62 through proper openings in the horizontal plate construction 74. The belts 62 and the pulleys 69 may have V-belt type construction and the pulleys 69 may support the bottoms of the belts to reduce friction on the plate construction 74. The pulleys 69 may be supported on shaft 69A. Any other desired construction may be used to support the belts 62 in a substantially level condition, as is obvious. For example, a series of pairs of pulleys like pulleys 69 may be used without the horizontal plate construction 74.

The top horizontal flanges 82 of angle beams 68 prevent upward movement of the beads 22 of the trays 12 and guide the tops of the trays while the belts 62 press upwardly on the bottoms 16 of the trays. The downward vertical side flanges of the angle beams 68 guide the sides of said receptacles, as shown in FIGURE 8. The frictional character of the tops of the belts 62 drive the trays 12 rightward, in FIGURES 6 and 7, until the front side 18 of the tray 12A contacts the right arresting barrier or plate 84 which stops the tray 12A and the tray 12B, etc., to the left of plate 84. At the proper time, the tray 12A

is released by the downward movement of plate 84 with a quick simultaneous upward movement of the left arresting plate 86 adjacent the rear side of the plate 12A. The upward movement of arresting barrier or plate 86 arrests the side 18 of tray 12B while tray 12A is free to travel rightwardly while being again driven by the friction belts 62. In the meantime, the tray 12B is arrested by the plate 86 until tray 12A has been carried beyond interference by upward movement of plate 84. The trays 12 are therefore sequentially released by the opposed and alternating upward and downward movements of the arresting plates 84 and 86 which act adjacent the front and rear sides of each succeeding leading receptacle of the series of receptacles that are being fed along the upper runs of the belts 62. The movements of these plates are correctly timed serially to arrest and to feed the trays as needed for proper operation of the machine.

The arresting plates 84 and 86 may be moved by the rocking bars 88 and 90 which are carried by a rectangular block or member 92 which is rocked on shaft 94 by any suitable mechanism 96 which may rock shaft 94, at proper times. The mechanism 96 may be actuated by the shaft 98 which in turn is driven by a chain construction 100, FIGURE 7, which is driven indirectly from the main motor 192 of the machine at the proper proportional speed to insure the proper feed of the trays in correct timed relation to the remainder of the machine.

For example, the mechanism 96 for rocking shaft 98 may include a disc 96 as shown in FIGURES 6A and 6B.

30 The disc 96 is secured to shaft 98 by flange 97 and screw bolt 97A. The disc 96 has a compound groove including a circular short radius groove 96A, a circular longer radius groove 96B, and quick movement, joining grooves 96C, which join the grooves 96A and 96B, and which cause the quick up and down movements of plates 84 and 86.

The rocking bar 90 may be provided with a roller 90A which is carried by a bracket or block 90B which is attached underneath the bar 90. The roller 90A extends into the grooves 96A, 96B and 96C and is actuated as the grooves rotate with the shaft 98.

The short radius groove 96A holds the roller 90A and the bar 90 in the upper position shown in FIGURES 6 and 6B, so the tray 12A, FIGURE 6, is prevented from moving rightward by the raised arresting plate 84. The tray 12A is arrested by plate 84 as long as roller 90A remains in short radius groove 96A.

When the tray 12A is to be released and the tray 12B, FIGURE 6, is to be arrested by plate 84, the roller 90A, FIGURES 6A and 6B, moves down as one of the quick movement grooves 96C passes the roller 90A. This quickly moves the bar 90 and plate 84 to their lower position where they are held for a relatively long interval of time during the engagement of longer radius groove 96B with roller 90A. The tray 12A is therefore quickly released by this downward movement.

At the same time the bar 88 and plate 86 are quickly moved up to their upper position as is obvious. The plate 86 therefore quickly arrests tray 12B before the tray 60 12B can move past the plate 86. The tray 12B is held in this arrested position during the time that longer radius groove 96B is engaging the roller 90A.

After the tray 12A has completely passed barrier plate 84, this plate 84 is raised to its upper position by the 65 passage of the other quick movement groove 96C past the roller 90A for reasons analogous to those already outlined. The plate 84 is then held in its upper position as long as the short radius groove 96A is engaging the roller 90A.

The plate 86 is being lowered quickly at the same time 70 that plate 84 is being raised. When the plate 86 has been fully lowered, the tray 12B, FIGURE 6, is released and travels rightward until it is arrested by the recently raised plate 84.

This releasing cycle is continuously repeated, so the 75 gates or plates 84 and 86 are alternately raised and low-

ered at proper times to feed trays 12 at the correct intervals of time.

In this manner the filled trays 12 are serially released by plate 84 at proper intervals of time to be delivered by friction belts 62 to the stationary tray feeding track construction 28, 29, and the tray pushing mechanism 30. The timing of the tray release is such that the released tray reaches the tracks 120, 122, FIGURE 7, at the correct time to be located between the pushing fingers 138 and to be properly engaged by one of the pushing fingers 138, as elsewhere described.

The arresting plates 84 and 86 are yieldingly pushed up and down by the surrounding spring construction 102 and adjustable nut or collar construction 104 to prevent the arresting plates 84 and 86 from unyieldingly puncturing the trays 12 if the plates 84 and 86 should strike the bottoms of the trays 12 before the trays have out of the way of plates 84 and 86. For example, a sprocket wheel 99 may be fixed to shaft 98 to be driven by chain belt 100. Belt 100 may be driven by sprocket wheel 101 which is fixed on and driven by shaft 184A which is elsewhere more fully described. Shaft 184A is driven indirectly by motor 192 as elsewhere described. The lower run of belt 100 passes under idler pulley 103, FIGURE 56.

The collars 104 may be fastened to the plates 84 and 86 by screw bolts 105, which are guided in slot constructions 107 in any suitable manner. The springs may bear on the rocking bars 88 and 90 at the spring bottoms and against the collars 104 and plates 84 and 86 at the spring upper ends.

The drive V-belt 106 may connect the expandable V-pulleys 108 and 110 which may be adjusted by turning of the knob 112 to vary the relative spread of the flanges of the pulleys 108 and 110. This is a well known construction on the market for varying the speed transmission from one shaft to another. Hence the speed of shaft 67 may be varied as desired, in relation to the speed of shaft 98. The speed of the friction belts 62 may thus be varied by this adjustment, which varies the speed of pulleys 66. This adjusts the speed of advance of the trays 12. The intervals of tray release, however, are governed by shaft 98.

The trays 12 may be fed into the entrance at the left end 116 of the angle beams 68, FIGURE 8, manually or by a conveyor belt 118, FIGURE 6, of any suitable type on which the trays 12 with the food contents or the like are placed automatically or manually, as desired from any source.

This construction provides frictional means or belts 62 frictionally to drive a plurality of trays or receptacles 12 in a generally horizontal direction. The two arresting plates or barriers 84 and 86 are alternately movable up and down serially to arrest and feed the trays as needed.

The flanges 82 are upward limit means to limit the upward movement of the trays 12.

The stationary tray or receptacle feeding track construction 28, 29 and the tray or receptacle pushing mechanism 30 are shown in FIGURES 1, 6-8, 8A, and 9-12.

These constructions 29 and 30 automatically feed trays into the tray or receptacle holding means or openings 134 of the orbital conveyor 38.

The tray feeding track construction or section 28 is made of two tray bottom supporting rods or tracks 120, FIGURE 8A, and two tray side guiding rods or tracks 122. These supporting rods 120 and 122 are tied together by a series of transverse rods 124 which may be welded to the rods 120, 122 at suitable intervals. The rods 120, 122 extend longitudinally along the machine from the left end 126 of the plate 74, FIGURE 7, to the gaps 128, FIGURES 9, 10 and 11 where the supporting rods 120 and 122 terminate and the supporting rods 130 begin. The rods 130 extend to the left end 132 of the tray lowering construction 32.

The tray feeding track constructions or sections 28 and

29 are substantially aligned and have gaps 128 between them.

The track construction 28 is generally similar to the track construction 56, FIGURES 29-32, elsewhere described.

The gaps 128, FIGURES 10 and 11, are for the purpose of permitting the plates 136 and 137 of the orbital conveyor 38 to pass from a position underneath the supporting rods 120, 122 of track or section 28, FIGURE 11, to a position above the rods 130 of the track construction or section 29. This permits the trays 12 which are being pushed leftward above and on the supporting rods 120 and 122 to be pushed past the gap 128 and on the rods 130, and along the tray lowering construction 32. Eventually the trays are deposited in tray or receptacle openings or holding means 134, FIGURES 2 and 12, of the orbital conveyor 38. The tray or receptacle bead 22 may rest on the plates 136, 137 of the orbital conveyor 38, FIGURES 2 and 14, if desired.

The belt-like tray or receptacle pushing mechanism 30, FIGURES 1, 6, 7, 9, etc., has pairs of downward and inward fingers 138 which are carried and moved by a pair of orbital chain belts 140 which push the trays or receptacles 12 rightward in FIGURES 1, 6, 7 and 9. The construction of the fingers 138 and belts 140 are substantially the same in principle and construction as in the pushing mechanism 58 shown in FIGURES 29-31.

The chain belts 140 are supported at their ends by sprocket wheels 142 and 144. The wheels 142 and 144 are fixed respectively to shafts 143 and 145. The upper spans of the chain belts 140 are maintained straight and are supported by the stationary horizontal bars 146, FIGURES 6 and 9. The bars 146 are adjustably carried by adjustment brackets 148 which are fulcrumed at 150 on side plates 152 and are held in adjusted position by nut and bolt constructions 154. The side plates 152 are carried by the uprights 155 and 157 of the frame work. The lower spans of the chain belts 140 are maintained straight and are supported or guided by stationary horizontal bars 156 and 158 which bars are supported by brackets 160 from the side plates 152.

The fingers 138 are fulcrumed on the chain belts 140 at 162', FIGURE 1. The upper ends of fingers 138 are fulcrumed at 164' to bracing links 166 which, in turn, are fulcrumed at 168' to the chain belt 140. This maintains the span runs of the belts 140 in straight condition, maintains the fingers 138 in proper vertical conditional along the span runs, and particularly the lower span run, and permits the chain belts 140 and finger constructions to turn at the sprocket wheels 142 and 144.

The tray pushing mechanism 30 pushes the trays or receptacles 12 rightward from the left end of the tray releasing belt construction 26, FIGURES 1 and 6, to a position where the trays 12 are deposited in the tray openings 134 of the plates 136 and 137, FIGURES 2, 11, 12 and 14.

The chain belts 140 are driven indirectly from the main motor 192. For example, the shaft 145, FIGURES 9 and 10, may be secured to a sprocket wheel 147 which is driven by a chain belt 149. The belt 149 may be driven by sprocket wheel 151 on shaft 233 which in turn is driven by belt 232 elsewhere described. An idler sprocket wheel 153 may be provided to hold the lower run of chain 149 on drive sprocket wheel 151. In this manner the pushing belts 140 are indirectly driven by shaft 233 and chain belt 232 which is indirectly driven from motor 192 in proper synchronism.

The tray or receptacle lowering construction 32, FIGURES 1, 11 and 12, receives the trays 12 from the supporting rods 130 of the tray feed back construction 29 at one level, FIGURES 11 and 12, and lowers said trays 12 to a lower level 36, FIGURES 11 and 12. The trays 12 are lowered from their upper position 12C in FIGURES 11 and 12 to the lower position shown at 12D in FIGURES 11 and 14, with their bead 22 in position 12D

resting on the edges of openings 134 of the plates 136, 137 of the orbital conveyor 38.

The lowering construction 32 may include a pair of rolls 162 which are rotatable about a pair of shafts 164, and which hold the trays 12 in their upper position 12C of FIGURES 11 and 12 and while the tray 12C is being pushed over the opening 134 of the plates 136, 137 of orbital conveyor 38. Another pair of eccentrically rotatable rolls 166 receive the tray 12C at the upper level 34 when the aligned surfaces 168 are in their upper position (not shown) and lower the tray to the position of tray 12D when the aligned surfaces 168 are in their lower position, as shown in FIGURES 11, 12 and 14. Thus causes the tray to rest in the opening 134 with its bead 22 resting on the plates 136 and 137 for transportation rightward to receive a cover as elsewhere described.

The rolls 162 and 166 may be driven at a proper speed ratio with respect to the drive of the orbital conveyor 38 by any suitable transmission means from the main motor 192. The rotation of the rolls 162 and 166 is such that the center of an opening 134 is substantially over the joining edges of rolls 162 and 166 when the aligned surfaces 168 are in their top position. The aligned surfaces are in their down position when the tray 12D reaches the position shown in FIGURE 11.

For example, a shaft 170 may be driven by a respective pair of sprocket wheels 172 which mesh with the two chain belts 174 of the orbital conveyor 38. The shaft 170 drives respectively the pair of bevel gears 176 which are adjustably fixed on shaft 170. The gears 176 drive bevel gears 178 which are fixed to the shafts 179 which drive the pair of sprocket wheels 180. The wheels 180 drive the pair of chains 182 and pair of sprocket wheels 184 which drive the pair of shafts 164 to rotate the rolls 162 and 166 in synchronism with the movement of the chains 174 of the orbital conveyor 38. The conveyor chains 174 are driven indirectly from motor 192 in proper synchronism.

This causes the upper surfaces of the pairs of rolls 162 and 166 to rotate outwardly away from each other, as indicated in FIGURE 12. This prevents any sidewise bias of the trays as they are being lowered, and causes the tray to be placed in the opening 134.

The stationary tray feeding track construction 28, 29 and the tray pushing mechanism 30 and the tray lowering construction 32 constitute tray receiving opening feed means automatically to feed trays 12 into the tray receiving openings 134 of the orbital belt 38 while the belt is moving.

The tray or receptacle supporting orbital conveyor or belt 38 has tray or receptacle holding means or tray receiving openings 134 is shown diagrammatically in FIGURES 1-5, 12, 14, 36, 37 and in other figures. The belt 38 is movable about an orbit which may be a vertical orbit.

The orbital conveyor or belt 38 has two similar chain belts 174 which extend longitudinally throughout a major portion of the machine. These belts 174 pass around two pairs of sprocket wheels 180A and 182A, FIGURES 1 and 3 at the intake and discharge ends of the belts 174. These pairs of sprocket wheels 180A and 182A are secured respectively to shafts 184A and 186A to cause the belts 174 to travel in unison. The shaft 186A is driven by pulley 188 and by chain belt 190 indirectly from the main motor 192 of the machine. The motor 192 may be provided with a variable speed transmission 194 which may be adjusted to produce varying rotation speeds in pulley 196 on shaft 197 of the transmission 196 by the adjustment of handle 198, FIGURE 4.

An electric brake 199 may be provided, such as on shaft 186A which may be applied automatically by any suitable type of control. For example, it may be automatically applied when the motor 192 is deenergized by the energization of solenoid 378, FIGURE 42, which

opens the switch 199A of the brake circuit. The brake 199 may be spring loaded to apply the brake whenever its operating solenoid 199B, FIGURE 42, is deenergized by opening of switch 199A. Any other type of control 5 may be used to operate brake 199. The brake may be made to be applied by energization of the solenoid, and deenergized by spring loading, if desired. The control circuit may then be altered, as is obvious, by causing switch 199A to close when switch 380 is opened in FIGURE 42. This causes the activating brake solenoid 199 to be applied when the motor is deenergized, in a manner to apply the brake.

The motor 192 and variable transmission 194 constitute a variable speed drive which is well known and is on the market, and hence the internal details thereof are not herein described. Any type of motor-variable transmission unit may be used for this purpose.

The chain belts 174 of the orbital conveyor 38 are therefore driven at adjustable speed by the sprocket wheels 20 182A at the discharge end of the conveyor 38.

The sprocket wheels 180A at the intake end of the conveyor 38 are mounted on a shaft 184A which is rotatable on a sliding adjustable bearing 200 which may be adjusted longitudinally of the conveyor 38 by set screw 202, FIGURES 1 and 11. The longitudinal tension of the chain belts 174 may therefore be adjusted to prevent slack, etc.

The upper spans of the chain belts 174 are supported and maintained in a substantially straight horizontal condition by the cooperation of the tray supporting plates 136, 137, FIGURES 3, 5, 12, 14, 36 and 37, their attaching brackets 204 which are connected to the chain belts 174 and the sliding action of the pads 206 of the plates 136 and 137. The pads 206 are supported on the stationary, straight supporting bars 208 which are rigidly supported in the machine by bracket construction 220, FIGURE 5. The supporting bars 208 extend substantially from the left end at wheels 172, FIGURE 11, to a point adjacent the sprocket wheels 182A at the discharge end of the orbital conveyor 38, as shown in FIGURE 3.

The orbital belt 38 is movable about a vertical orbit. It has a substantially straight horizontal tray supporting run which extends substantially from sprocket wheel 172, FIGURE 1, to sprocket wheel 182A, FIGURE 3. The belt 38 has its tray receiving openings 134 movable along such run. The openings receive the trays 12 at 45 166, FIGURES 9 and 11, with covers over them adjacent cover feeder 250, FIGURES 15 and 16, along the horizontal run.

As illustrated in FIGURES 1, 3, 5, 11, 36 and 37, the central position of brackets 204 on the plates 136 and 137 and their attachment to the chains 174 permit the plates 136 and 137 to travel around the sprocket wheels 180A and 182A as well as sprocket wheels 172, 210 and 55 212 at the bottom runs of the chain belts 174. The wheels 210 and 212 idle on shafts 214 and 216 respectively. Bars 218, FIGURES 1, 3, and 5, at the bottom of the machine support the lower runs of the chains 174 to maintain the chains in substantially straight 60 horizontal condition without substantial zig.

The bars 208, FIGURE 5, are supported by a series of bracket constructions 220 and bars 222 which extend from the square tube main frame members 224.

The chain belts 174 and the plates 136 and 137 pass 65 through the gap 128, FIGURE 11, while the belts 174 travel from the sprocket wheels 180A to the sprocket wheels 172, so the orbital conveyor construction can pass upwardly from its bottom run to its top run, where it receives the trays 12 in its tray openings 134 to transport the trays from the feeding construction 26, 28 and 29 to the tray and cover securing mechanism 48.

The conveyor 38 has a plurality of pairs of tray carrying plates 136 and 137. These plates 136 and 137 of each pair have adjacent edges 136A and 137A respectively, FIGURE 37. These edges have notches 136B and

137B respectively which form the tray receiving opening 134. This construction permits the chains 174 and plates 136 and 137 to pass around relatively small sprocket wheels and yet provide relatively flat tray receiving openings along the horizontal run of the conveyor 38.

The tray or receptacle absence sensing means 40, 42, etc., FIGURES 1, 13 and 14, controls the machine in response to any accidental absence of a tray 12 from an opening 134 of the orbital conveyor 38, where such tray ordinarily should be.

The tray absence sensing means 40, 42 may control the machine by preventing a cover feeding action to prevent a cover 10 from being fed from the sheet cover feeding means 44, FIGURES 1, 15 and 16, into the correspondingly empty opening 134 of the conveyor 38.

The tray absence sensing means 40, 42 may be located at a point in the rightward travel of the upper run of the conveyor 38 adjacent the tray feeding action which normally places a tray 12 in the tray receiving opening 134 of the conveyor 38. For example, the sensing means 40, 42 may be located adjacent the point where the lowering rolls 166, FIGURE 13, lower the tray 12 into the opening 134 of the conveyor 38, such as shown at 12 in FIGURE 13.

The members 40 and 42 may constitute any type of electric eye or ultrasonic, high frequency wave action, couple which detects whether a tray 12 is in or absent from the particular conveyor tray opening 134 which happens to be passing between the members 40 and 42. If there is no tray in such opening 134, then the cover feed drive belt 226 is prevented from operating and feeding a cover 10 for the missing tray 12 at that time. Stopping belt 226 also stops the cover feed actuator pulley 228 which drives any dominant part of the cover feed mechanism. By this construction, there will be no cover 10 ready to feed into the empty tray opening.

By way of example, a chain belt 232, FIGURE 13, is driven by a pulley 234 on shaft 216 which in turn is driven by the sprocket wheel 212, which is actuated by the chain belt 174 of the conveyor 38. The belt 232 drives the pulley 236, FIGURE 14, on shaft 233 at the rate of one complete revolution for each passing tray opening 134. A disc 237 which is fixed on shaft 233 has a tooth 238 which normally drives the actuating lever 240 which is mounted on the disc construction 242 which drives the cover feed belt 226 by means of sprocket wheel 243. Sprocket wheel 243 drives chain belt 226, FIGURE 1, which drives the cover feeder mechanism.

The disc construction 242, FIGURE 13A, carries the actuating lever 240 with a fulcrum at 248. The lever 240 is urged clockwise about the fulcrum 248 by a tension spring 247 which is connected to the lever 240 at 245 and to the disc 242 at 245A. As long as the pin 246 is not forced down, the tooth 249 on lever 240 engages the tooth 238 on the disc 237. This permits the disc 237 to rotate the disc 242 clockwise. The disc 242 is attached to the sprocket wheel 243 and also rotates the wheel 243 clockwise. The wheel 243 drives the chain 226 and the cover feeder mechanism 44 elsewhere described. One revolution of the disc 242 and sprocket wheel 243 feeds one cover 10 to one passing tray 12 as elsewhere described.

However, if the pin or rod 246 is held down by the absence of a tray 12 then the lever 240 is rotated counter-clockwise about the fulcrum 248 so that tooth 249 is disengaged from tooth 238. When this happens, rotation of disc 237 fails to rotate disc 242, sprocket wheel 243 and chain belt 226. This prevents the feeding of a cover 10 by the cover feed mechanism 44. The absence of a cover 10 at the cover feeding trough causes the main motor 192 to be stopped until the proper corrections have been made.

Therefore if there is no tray in a tray opening 134 of the conveyor 38, then the ultrasonic couple 40, 42 is

actuated by the passage of ultrasonic waves between the members 40 and 42, and through the empty tray opening and this in turn actuates an electrical circuit which energizes the solenoid 244. The solenoid pushes the rod 246 down by solid offset member 247 to rock the actuating lever 240 about its fulcrum 248 so the tooth 238 cannot engage the tooth 249. The lever 240 therefore does not drive the construction 242 or the cover feeder belt 226 during the one revolution which corresponds to the empty tray opening 134 in conveyor 38. This stops a cover feeding action while an empty tray opening 134 is passing between sensing members 40 and 42. Therefore there is no feed of a cover 10 for the absent tray 12, and no feed of such cover into the corresponding empty spaces 134.

The absence of a cover 10B between the ends of the fingers 308 and 310, FIGURES 38, 43 and 44, stops the main motor 192 and the operation of the machine, as elsewhere described, until precautions are taken to correct the disorder.

The normal cover feed is restored as soon as trays are properly fed into the tray openings 134, and the machine is "inched" to the next tray opening with a tray in it.

The ultrasonic members 40 and 42, the solenoid 244 and the actuating circuits between such members constitute an article of commerce, per se, now on the market, and hence internal details thereof are not here further described.

The sheet cover feeding means 44, FIGURES 1, 13-18, and 36-41, etc., is provided for automatically feeding covers 10, FIGURES 33 and 34, at the rate of one cover 10 for each tray or receptacle 12 which is carried by the tray openings 134, FIGURES 36 and 37, of orbital conveyor 38.

Such feeding means 44 may be supported on a frame 45, FIGURES 13 and 16, and may include any suitable type of trough 250, FIGURES 1 and 38, which receives a cover 10A, FIGURE 38, as it is cut and released by the cover cutting device 252, FIGURE 1. The cover 10A is received and is fed to the cover moving means 46, including fingers 308 and 310, elsewhere described. The cover moving means carries a cover over a tray 12 in the relationship shown in FIGURE 33 longitudinally along the machine to the cover and tray securing mechanism 48, where the edges of the cover are folded around the tray.

For example, a cut cover 10A falls into the funnel-like part 254, FIGURES 38 and 39, of the trough 250. Such cut cover slides down the trough 250 to the position of cover 10B, FIGURES 38-41, where it is stopped by the gate 256 when the gate is in the down position, as shown in full lines in FIGURES 38-41. The trough 250 is sufficiently horizontal at its lower end so the cover 10B remains substantially stationary after the gate 256 is swung to the up, dotted line position 256A, FIGURE 38. The cover 10B is now ready to be taken by grasping fingers 310 and 308 of the cover moving means 46, more fully elsewhere described. The cover 10B is then moved, in unison with a tray 12 underneath such as cover 10, to the cover and tray securing mechanism 48, elsewhere more fully described, there to be raised into the securing mechanism to fold and secure the edges of the cover 10 around the edges of the tray 12.

The covers 10 are cut and fed downwardly into the trough 250 by any suitable cover cutting and feeding means. Any type of cutter and feeder may be used, whether now known or not. For example, a suitable strip cutter and feeder mechanism, now well known per se, is illustrated diagrammatically at 258 in FIGURE 1. Such mechanism may include a frictionally held foil roll holder 260 which feeds the aluminum strip 262, or the like and of correct width, past the axially fixed rolls 264 and the axially movable, slack compensating rolls

266 to the foil smoothing rolls 268 which are covered with rubber or the like. The rolls 266 are tightened by spring 267 which pulls the roll frame 269 about the fulcrum 271. The strip passes into the intermittent feed rolls 230 which feed the strip 262 at a rate to supply suitable lengths of foil to be cut into correct lengths of covers 10A by the cover cutting device 252. The cover cutting device 252 may include a rotatable knife roll 251 with rotatable knife 251A which acts with non-rotatable knife 253 to cut covers 10A of proper length and width. The illustration in FIGURE 1 is diagrammatic but will be recognized by those skilled in the art. The covers 10A, FIGURES 1 and 38, are cut and supplied to the trough 250 in timed relation to the rightward travel of trays 12. A cover 10B, FIGURE 38, slides to correct position against the gate 256 so the gate may be swung upwardly to the dotted line position 256A at the correct moment to permit the diagrammatically shown grasping finger 310, FIGURE 38, which cooperates with finger 308 elsewhere described and shown, automatically to carry the cover 10B rightwardly along the machine over a tray 12 for wrapping of the cover around the tray in cover and tray covering mechanism 48, elsewhere described. The frame 45 is illustrated as substantially horizontally mounted in FIGURE 1, etc., on the machine. However, it may be slanted downwardly at the right and if desired, more easily to mount it on the machine.

The trough 250 may be of any suitable construction. For example, it may be made of a suitably curved sheet 259 to which suitable trough forming members 261 may be attached. Openings 263 are provided to receive bolts 265 or the like for securing the trough 250 to a suitable support 267, FIGURE 1, which is supported by the main framework of the machine, such as members 224, etc.

The gate 256, FIGURES 1, 15, 16, 17, 38 and 40, is carried by a rockable shaft 270, which shaft causes the gate 256 to be opened upwardly or closed downwardly by rocking movement of the shaft 270. The shaft 270 may be rocked by any suitable means. For example, the shaft 270 may have a lever 272, FIGURE 16, at one end which is moved up and down by another lever 274 through the medium of a link 276. The lever 274 is fulcrumed at 278 on a stand 280.

The lever 274 is rocked up and down by a cam 282, FIGURES 16 and 17, which is driven at the correct speed to open the gate 256 at the desired time for removal of the tray cover 10B, FIGURE 38, by the grasping finger construction 310. For example, the cam 282 moves the vertical rod 284 up and down by actuating the pin 284 and lever 286 which has a fulcrum at 287. The rod 284 is secured at 288, FIGURE 16, to the lever 274, which is indirectly connected to gate 256, to rock the same as previously described. The cam 282 is driven by the shaft 290 which in turn is driven by the bevel gears 292 from the shaft 294. The shaft 294 is driven indirectly from the shaft 296, FIGURE 19, through the medium of chain 297 and sprocket wheels 298 and 300.

The trough 250, FIGURE 38, is cut at the corners 301, so the uncut corners 303 of the cover 10B can be grasped by the grasping construction including lower finger 310, elsewhere described. The cover 10B is then pulled along by its leading corners 303 over a tray 12 so the cover and tray may be moved together to means 48 later to be described.

The shaft 296 may be driven by bevel gears 302, FIGURE 19, one of which may be drivingly connected by suitable gearing and shafting to the pulley 304, which is driven by a chain 306 indirectly, as described, from the main motor 192. The chain 306 is driven by a sprocket wheel 305 on shaft 500 which is rotated indirectly from motor 192 as elsewhere described. A similar chain 297 and sprocket wheels 298 and 300, shafts 294 and 296, bevel gears 302 and belt 306, etc., are provided on the other side of the vertical median plane of the machine,

which, however, do not drive a gate mechanism, but do drive the grasping finger constructions 308, 310, on each side of the median plane as elsewhere described.

FIGURES 1, 3, 5, 15-19, 33, 34, 38, 43 and 44 are the more pertinent illustrations of this mechanism.

The moving means 46 moves the horizontal covers 10 over the horizontal trays or receptacles 12, FIGURES 33 and 34, from the right end of the trough 250, FIGURES 1 and 38, laterally to a position under and substantially at the center of the securing mechanism 48 where the sprocket wheel 300 and shaft 296 are shown in FIGURE 3. At this point the covers are released and the covers 10 and trays 12 are raised into the mechanism 48 in which the covers 10 are wrapped around the edges and corners of the trays 12.

The moving means for the covers 10 are in the form of grasping fingers 308 and 310, FIGURES 43 and 44. These fingers have grasping neoprene pads 312 at their ends to grasp the covers 10 at their leading corners, as shown in FIGURE 38. If desired, insulation resilient pieces 360 and 362 may be added or substituted. Pins 358 may be placed in the insulation pieces 360 to aid in sensing the failure to grasp a foil cover 10, as elsewhere described. The fingers 308 and 310 are biased toward each other by tension spring constructions 311 which are attached to bars 313 and 315 which are attached respectively to the fingers 308 and 310. The upper finger 308 is not movable up or down, but the lower finger is movable about a fulcrum at the point 314, FIGURES 17 and 44. The lower finger 310 has a shorter arm 316 by which the longer outer arm 317 of the lower finger 310 is quickly moved downwardly and is held away from the upper finger 308 while the fingers move around the arcs 318, FIGURE 18, from the radius 320 to the radius 322, more or less. This permits the lower fingers 310 to travel under the trough 250, FIGURE 38, while the upper fingers 308 travel above the trough 250 and over the cover 10B, FIGURE 38, until the fingers reach the corners 301 of the trough 250. When the fingers reach this point, the lower fingers 310 snap upward and push the corners 303 of the cover 10B, FIGURE 38, up against the upper fingers 308 so that the corners 303 are grasped between the pads 312 and/or pins 358 and insulation pieces 360 and 362, FIGURES 43 and 44, of the fingers 308 and 310. The cover 10B is pulled along rightward in FIGURE 38 over a tray 12, not shown, which is moving under the cover at the correct moment.

The trough-forming members 261 are cut away at 324 to permit the upper fingers 308 to swing over the cover 10B and over the tower end of the trough 250 so the cover 50 10B can be located between the fingers 308 and 310. The lower finger 310 is moved up and down by the engagement of the shorter arm 316 with a wire cam formation 326 which is low enough at 328 to go under the short arm 316 and then rises high enough at 330 to raise the 55 short arm 316 and lower longer arm 317 of the finger 310 so the longer arm 317 of finger 310 travels under the trough 250. The wire cam 326 ends at 319 as shown in FIGURE 19, so the short arm 316 and the lower finger 310 are released by the cam 326 so the long arm 317 and 60 finger 310 can snap up and grasp the corner 303 of the cover 10B.

A cover-releasing or reverse action is produced in the grasping finger construction at the positions 332, FIGURES 18, 19, 43 and 44. When the fingers 308 and 310 65 reach the positions 332 the longer arms 317 of the lower fingers 310 are quickly forced downwardly by the wire cams 334 which have a high position at 335 and a low position at 336. The short arms 316 of the lower fingers 310 pass over the wire cam at 336 and are then pushed up 70 at 335 thereby causing longer arms 317 of the fingers 310 to be lowered and to release the cover 10 which has been carried along from the grasping point at the corners 301 at the left end of FIGURE 18 to the release point 332 at the right end of FIGURE 18.

75 The released covers 10 and corresponding trays 12

are then raised into the securing means 48 later to be described.

The fingers 308 and 310 slide along the bars 338, FIGURES 17, 43 and 44 which are engaged by the grooves 340 of the blocks 341 of the finger constructions. The chains 297 are attached to the blocks 342 of the finger constructions by brackets 344 so the ends of the fingers 308 and 310 are moved about their orbits 346 as indicated by the arrows 348' in FIGURE 18.

The wire cams 326 and 334 are supported at extensions 348, FIGURES 18, 43 and 44 by adjustable supports such as illustrated at 350', which are attached to any suitable frame work 352', FIGURES 17, 18 and 19.

The upper finger 308 has a downward leg 308A which abuts against the block 341 and is secured thereto by one or more screw bolts 308B.

The lower finger 310 has a rectangular ring or band 310A which surrounds the block 341 and is fulcrumed by pin 314 to such block 341. One end 310B of the ring 310A is attached to or is integral with the longer arm 317 of finger 310. The other end 310C of the ring 310A is higher than the end 310B and is attached to the shorter arm 316 of finger 310. The rectangular ring 310A has an upward offset at 310D.

Any suitable circuit may be used to actuate the cover absence sensing mechanism 50. A suitable cover absence sensing circuit is shown in FIGURE 42.

This circuit may be of any type which causes the machine to be modified such as to be stopped when there is no cover foil 10 in the cover grasping fingers 108 and 110 during the selected sensing time. The selected sensing time may be soon after the grasping fingers 108 and 110 should have received and gripped a foil cover 10B, FIGURE 38, to carry it along and over a tray 12 to be covered.

For example, the sensing circuit of FIGURE 42 may have a low voltage foil cover sub-circuit 352 which is sensitive to the presence or absence of a foil cover 10 between the grasping fingers 108 and 110. The low voltage circuit 352 may include the modified fingers 108, the foil cover 10, the coil 353 of relay 354, stationary strip contacts 356 which are placed over the path of the ends of the fingers 108, contact pins 358 which contact the stationary strips 356 as the fingers pass along under such contacts. A battery or step down transformer 355 may be included in the low voltage circuit 352. The pins 358, FIGURES 42 and 44, are held and insulated in insulating resilient insulation pieces 360 built into the ends of the fingers 108. The pins 358 are constructed to have their lower ends hold and contact the cover foil 10 or else contact the lower insulation pieces 362 which are built into the lower gripping fingers 110. The contacts 364 of relay 354 are opened when there is a foil cover 10 in the fingers 108, 110 because the battery circuit 352 is completely closed and the coil 353 of the relay 354 is energized to pull up and open the contacts 364.

The absence of a foil cover 10 in the fingers 108, 110 breaks the battery circuit 352 and thus deenergizes the circuit 352 and coil 353 and closes or drops the contacts 364 to close part of the sub-circuit 366. The remainder of the sub-circuit 366 includes the switch 368 which is closed by cam 371 at a selected sensing time during the travel of the fingers 308, 310. The cam 371 may be rotated by any desired connection with the actuating mechanism of the fingers 308, 310 to close the switch 368 at the proper sensing time, when it is desired to sense the presence or absence of a foil cover 10. For example, the cam 371 may be driven by one of the vertical shafts 294, FIGURE 1. The cam 371 may be enclosed in a box 371A along with switch 368 to close the switch 368 at the proper time. This sensing time may be a short interval just after the fingers have passed the cover feed trough 250.

The complete closing of the sub-circuit 366 by the absence of foil 10 during the sensing interval energizes

the coil 367 of relay 369 and closes the relay contacts 370 and 372. The upper contacts 372 are part of another sub-circuit 374 which is connected to line L at 375. The lower contacts 370 are a part of another sub-circuit 376 which is connected to line La at 377. The sub-circuits 374 and 376, when closed, energize the coil 378 of relay 379 which in turn opens the on-and-off switch contacts 380 of the main motor 192 which drives the machine.

The low voltage circuit 352 does not have control of the main motor 192 except during the sensing interval when the cam 371 closes the switch 368. When the switch 368 is open, during non-sensing time, the low voltage circuit 352 cannot control motor 192 because relay 369 cannot be energized by circuit 352 and circuit 366 as long as sensing time switch 368 is open.

The motor 192 may also be manually energized by a manual push-pull, off-and-on switch handle 382.

The switch handle 382 opens and closes the contacts 383 by snap action to energize or de-energize the relay 20 coil 378 and motor 192.

In operation of the "no cover foil" sensing circuit of FIGURE 42, a foil cover 10 is normally fed between the grasping fingers 108, 110 to be pulled by its front corners 303, FIGURE 38, over a tray 12 to the cover securing 25 and crimping mechanism 48 elsewhere described.

If the cover foil 10 is properly grasped by the fingers 308, 310 and the pins 358, the main motor 192 of the machine is not stopped during the sensing time, because the battery sub-circuit 352 is energized to energize relay 30 354 and to open its contacts 364 which are in sub-circuit 366. The opening of contacts 364 prevents the closing of sub-circuit 366 which prevents any automatic stopping of the main motor by the relay 369, contacts 370, 372, sub-circuits 374 and 376, and relay 378.

However, if there is a failure properly to feed a foil cover 10 between the fingers 308, 310 during the sensing time established by the closing of switch 368 by cam 371, then the main motor 192 is stopped by the following chain of actions. Sub-circuit 352 is maintained open 40 during the sensing period by the absence of foil between fingers 308, 310. This closes contacts 364. The switch 368 is closed by cam 370 during the sensing circuit. Closing of contacts 364 and 368 simultaneously during sensing time energizes the coil 367 of relay 369, which in turn 45 closes contacts 370 and 372 and energizes sub-circuits 374 and 376. Energization of sub-circuits 374 and 376 energizes the coil 378 of relay 379 and opens the main motor contacts 380 to stop the main motor 192 which in turn 50 stops operation of the machine.

A brake may also be energized at this time by the de-energization of the motor circuit. For example, switch 199A may be opened when the motor switch 380 is opened. The electric brake 199 is then automatically applied when its solenoid 199B is de-energized, as more 55 fully elsewhere described.

If desired, the machine may be operated by manually pushing handle 380 of normally spring closed switch contacts 381. This opens the control circuit to coil 378 and permits the contact 380 to drop to closed position 60 and energize the main motor 192, regardless of any stopping control at push-pull switch 382 or "no foil" switch circuit 352. This permits the machine to be "inched" to another position by pushing handle 380 after the absence of the cover 10 is corrected by the removal of the coverless tray 12 from the machine or by any other 65 correcting process.

The safety relay 386 has its solenoid 387 placed across the lines L-La so its closes the safety switch 388 as long as there is power in line L-La and opens the switch 388 if line L-La should become de-energized. If the line L-La should become de-energized for any reason, such as because of power failure, broken line, etc., then the solenoid 386 becomes de-energized and drops the switch 388 to open position and thus cuts off the main power 70 to the main motor 192 regardless of the switch positions

in the control circuit. Hence undesired or dangerous operation of the main motor 192 is prevented.

Any other circuit arrangement capable of obtaining the same results may be used.

The cover and tray securing mechanism 48

The cover and tray or receptacle securing mechanism or means 48 is placed above a portion of the orbital conveyor 38, as indicated in FIGURES 1 and 3. It is a cover wrapping means automatically to wrap the covers 10 around the tops of trays 12.

FIGURES 1, 3, 5, 20-22, 24-28 and 48-51 show this mechanism 48.

A framework 400, FIGURES 20, 22 and 48, is provided for the cover and tray securing mechanism 48 and is placed above the upper run of the orbital tray supporting conveyor 38. The framework 400 carries four horizontal shafts 401, 402, 403 and 404, FIGURE 22, which carry sprocket wheels 406 at their inner ends. The sprocket wheels 406 drive chain belts 408 which form an orbital conveyor construction which drives or moves the tray and cover securing or wrapping units 410 by means of pin-like constructions 434, FIGURES 24 and 25.

The units 410 carry rollers or guiding protrusions 412 at their forward and back corners, or opposite ends, FIGURES 24, 25, etc. These rollers ride between straight horizontal bars 414 and 416, FIGURES 5, 21 and 48, which are located along the upper straight run of the orbital conveyor formed by the chain belts 408. The rollers 412 also ride between the straight horizontal bars 418 and 420, FIGURES 5, 21 and 48, which are located along the lower horizontal straight run of the orbital conveyor construction formed by the chain belts 408. This lower straight run is parallel to the upper straight horizontal run of conveyor 38.

The chain belts 408 constitute a tray and cover wrapping unit moving orbital belt construction which is movable about a vertical orbit and has a substantially straight horizontal operating run between the sprocket wheels 401, 402, 403 and 404 which is parallel to the upper horizontal run of the conveyor belt 38.

The bars 414, 416, 418, and 420 merge at the ends of the straight runs with the curved groove pieces 422, 422A, 423 and 424, FIGURE 48, at the ends of the straight runs so the rollers 412 are guided down and around in arcuate grooves or guiding means 425 and 427 at the left ends of FIGURES 20, 21 and 48 and are similarly guided up and around at the right end of FIGURES 20 and 48. These grooves 425 and 427 are provided at all four corners of the securing mechanism adjacent shafts 401, 402, 403 and 404 of FIGURE 22. The groove pieces 422 and 422A may be joined by a rear wall 425A, as shown in FIGURE 49.

In this manner the units 410 are caused to travel leftward along the upper runs of the chain belts 408, as indicated by the arrow 426 in FIGURES 20 and 48 and rightward along the bottom runs of the chain belts 408 as indicated by the arrow 428 in FIGURES 20 and 48.

There are sufficient units 410, FIGURE 48, carried by chain belts 408 and bars 414, 416, 418, and 420 so there is a unit 410 for each opening 134, FIGURE 48, of the orbital conveyor 38. In the particular embodiment illustrated in FIGURES 20 and 48, there are six units 410.

These units 410 remain horizontal with the same sides down during their entire travel along the straight runs of the chain belts 408 and along their curved descent, at the left end, as shown in FIGURES 21, 48 and 50, and along their corresponding curved ascent at the right end of FIGURES 20, 22 and 48. Thus the tray and cover wrapping units 410 remain with their sides facing the same direction as said units are moved throughout the orbit of said wrapping unit moving orbital construction.

The units 410 travel rightward in FIGURES 1, 20, 22, 48, etc., in their lower horizontal path or run, as indicated by the arrow 428 in FIGURES 20 and 48 at the same

speed as and in synchronism with the openings 134 of the orbital conveyor 38 and with the trays and covers. The units 410 remain correctly disposed over such openings 134 so the trays 12 and covers 10 may be raised up into the units 410 by the lifting platforms 482. The covers 10 are wrapped around the edges and corners of the trays in the units 410, as elsewhere more fully described. In this manner, means are provided for causing relative movement between the trays with covers and said wrapping units 410 to place the trays and covers in said units.

The shafts 401, 402, 403, 404, sprocket wheels 406 and chain belts 408 may be driven indirectly from motor 192 by any suitable means. For example, the shafts 401 and 402 may be provided with sprocket wheels 405 which are driven by chain belts 407. The belts 407 are driven from sprocket wheels 409 which are fixed on shaft 500. The belts 407 also pass around idler sprocket wheels 411A on idler shafts 413A. The shaft 500 may be driven by fixed sprocket wheel 415A which is driven by chain belt 417A which is driven by sprocket wheel 419A which is fixed to shaft 186A which is driven from motor 192, as elsewhere described.

FIGURES 5, 24-28, 45, 47, 49 and 51 show details of the units 410.

The units 410 have a generally rectangular main plate 430 which is secured to side angle pieces 432, FIGURES 24 and 25, to which the roller constructions 412 are secured near the corners of the units 410. Also, the chain attaching pin-like constructions 434 are connected to the angle pieces 432 and to the chains 408. In this manner, the units are carried and moved horizontally as indicated by arrows 426 and 428, FIGURE 48, as previously described.

The units 410 have side wrapping rollers 436, FIGURES 24 and 25, and front and rear similar edge wrapping rollers 438 rock about the pins 440, FIGURES 24-28 and 45. These rollers have a longitudinal ledge 442, FIGURE 27, with a longitudinal wrapping tooth 444.

A trap 12 and cover 10, FIGURES 26-28, are moved upwardly into the space between the rollers 436 and 438 by the lifting platform 482. As the trays move upwardly past the bulges 446, FIGURE 27, the overhanging edge 448 of the cover 10 is bent partly around the bead 22 of the tray 12, as shown in FIGURE 27. Then the rollers 436 and 438 are simultaneously rocked to the position of FIGURE 28. This causes the longitudinal tooth 444 completely to wrap the edge 448 of cover 10 around the bead 22 of tray 12.

The rollers 436 and 438 are biased to open position, such as shown in FIGURE 27, by the reciprocable pins 450 which bear against the upper parts of the rollers 436 and 438 when pushed by the compression springs 452.

However, before the wrapping action of FIGURES 26 and 27, the edge corners of the covers 10 are bent around the corners of the trays 12 by the means shown in FIGURES 26, 45, 46, 47 and 51 taken with FIGURES 24, 25 and 49.

A wrapping plate 454, FIGURES 26, 45, 46, 47 and 51 at each corner of the unit 410 is part of corner cover 60 wrapping member 453 and is moved toward the center of the unit 410 by a supporting block 456 which moves in and out along the long slot 458 and slides under the main plate 430 of the unit 410. The block 456 is carried by an upper plate 460 which fits in the opening 458 and

65 which has outwardly extending flanges 461 which slide and rest on top of plate 430. In this manner, the wrapping plate 454 can move diagonally in and out under the corners of the tray 12 to fold the corners 464, FIGURE 26, of the edge of the cover 10. This corner wrapping in FIGURE 26 takes place before the side wrapping at 448 in FIGURES 27 and 28.

The wrapping plate 454, FIGURE 47, has a corner curve 457A which aids in the wrapping operation.

The wrapping plate 454, block 456 and supporting 75 plate 460 are pushed outwardly by compression spring

466, FIGURES 26, 45, 46 and 47, which is placed between the block 456 and a stationary block 468 which straddles the slot 458 and is attached to the under side of main plate 430.

The corner members 454, 456, and 460 are pulled inwardly along the slots 458 by the links 470, FIGURES 24 and 49, which are supported above the main plate 430. The links 470 are attached to plates 460 by pins 472 and washers 473, FIGURES 45 and 46. The links 470 move the plates 460 from the outer position shown on the right side of FIGURE 24 and in FIGURE 49, to the inner folded position shown on the left side of FIGURE 24. This motion is produced by the movement of links 470 from a straight line position on the right side of FIGURE 24 to the folded position on the left side of FIGURE 24. This action wraps the corners of the covers 10. The actuation of links 470 is elsewhere described.

Pairs of the links 470, FIGURES 24, 25 and 49, are secured to each other by pins or pin constructions 474 which pass through the links and are secured to the flanged block 476 which block moves in and out in the groove 478 when the roller 480, FIGURE 25, is moved back and forth by the stationary operating grooved means 54, FIGURE 22, elsewhere described, to cause the covers 10 to be wrapped and secured to the edges of the trays 12.

Star wheel or gear wheels 413 and/or 413D, FIGURES 49, 50, 53 and 54, may be used to hold a pair of the rollers 412 of units 410 in proper position as such rollers 412 descend and/or ascend through the curved grooves 427 (and/or 425) at both ends of the framework 400. Alternately, such star or gear wheels 413 and/or 413D may engage protrusions similar to rollers 412, such as the shafts of the rollers 412. Such shafts are indicated at 412A and 412B in FIGURE 49.

For example, FIGURES 49, 50 and 53 show an arrangement suitable for a star or gear wheel or construction 413 on each side of a cover and tray securing unit 410. These star or gear wheels may be provided at all four corners A, B, C and D of the framework 400 of FIGURES 22 and 49. FIGURES 49, 50 and 53 more or less specifically illustrate the construction in connection with corner A, but is also applicable to the other corners B, C and D.

In FIGURES 49, 50 and 53, shaft 404, gear 406, chain belt 408, rollers 412, groove pieces 422 and 423, straight horizontal bars 414, 416, 418 and 420 and pen-like constructions 434 may all be the same as previously described. However, the groove piece 424 may be omitted.

An additional cantilever shaft 411 is mounted at each corner of the framework 400 and carries a star or gear wheel 413 adjustably fixed thereto. Preferably, the gear wheel 413 has sprocket grooves 415 which are identical in number and spacing with the sprocket grooves 417 of sprocket wheel 406. The rollers 412 are made of a size and are spaced from the pin-like constructions 434 so the pin-like constructions 434 may fit into a groove 417 of sprocket wheel 406 at the same time that the roller 412 fits into a groove 415 of sprocket wheel 413, as shown in FIGURE 50. The shaft 411 may be driven by sprocket wheel 419 which is adjustably fixed on shaft 411, chain belt 421 and sprocket wheel 423A which is fixed on shaft 404. Sprocket wheels 406 and 413 are thus synchronized so a roller 412 of unit 410 fits into a sprocket groove 415 at the same time that pen-like construction 434 fits into a sprocket groove 417 in sprocket wheel 406.

The roller 412 and pen-like construction 434 follow each other in exact relationship all the way from the top position of FIGURE 50, through the intermediate position of FIGURE 53 and down to the bottom position, not shown, which is 180° from the top position of FIGURE 50.

In this manner, the sprocket groove 415 which engages the roller 412 firmly holds the roller 412 in the interмеди-

ate position of FIGURE 53 from any substantial up and down play within the groove 415. Hence the unit 410 is firmly held in horizontal position by the pen-like construction 434 on sprocket wheel 406 and the roller 412 and groove 415 on sprocket wheel 413. This is accomplished because the wheels 406 and 413 are held in fixed rotation relationship by the chain drive 421. Member 423 prevents roller 412 from jumping from one sprocket groove to another.

The left roller 412 at the left end of the unit 410 in FIGURES 49, 50 and 53 is also correctly spaced with respect to the length of the links of chain 408 and grooves 417 and 415. The spacing is such that the said left roller can pass horizontally and temporarily engage a groove 415 as it passes sprocket wheel 413. However, the left roller 412 can continue horizontally past the sprocket wheel 413 and can continue into the groove 425 of groove piece 422. The straight bars 414 and 416 and the right roller 412 maintain the unit 410 in horizontal position as the left roller 412 passes over sprocket wheel 413.

In this manner, the unit 410 is held horizontal in FIGURE 53 in spite of the tangential play which the left roller 412 would otherwise permit. The left roller 412 and the construction or shaft 434 force the right roller down into "groove" 427A as the unit 410 starts its downward travel.

The same principles apply to the other side of the unit 410 at sprocket wheel 413, etc.

The same principles apply on the upward travel of the units 410 at the other end of framework 400.

When the units 410, FIGURE 48, are on the rising ends of the chain belts 408, such as at the right end of FIGURE 48, the right end rollers 412 of the units become the leading rollers and enter the grooves 425 and the left end rollers become the rear end roller and enter the grooves 427. However, these same rollers 412 entered the inner groove 427 at the left end of the chain belts 406 on the downward movement of the same unit 410.

The same change occurs in the embodiment of FIGURES 49, 50 and 53. That is, the rollers 412 which engage the gear wheels 413 at the left ends of chain belts 408 do not engage the corresponding gear wheels 413 (not shown) at the right ends (not shown) of the belts 408. Instead, these same rollers will engage the groove 425 at the right ends of the belts 408.

If desired, the gear or star wheels 413 of FIGURES 49, 50 and 53 may be placed outside (to the left) of the gear wheels 406 instead of on the inside. For example, in FIGURE 54, the gear wheel 413D may be placed on the outside, (to the left) of gear wheel 406. In such a case, the groove forming members 423 and 424 are used to form the inner grooves 427. The member 422D has no rear wall at 425D (such as shown at 425A in FIGURE 49) and has no inner groove forming member where the grooves 415D of gear wheel 413D operates. The drive shaft 411D may be driven in the same manner that shaft 411 is driven in FIGURES 49, 50 and 53, except that the shaft 411D is to the left of shaft 404 instead of to the right. Chains similar to 421 and sprocket wheels similar to 419 and 423A may be used, as is obvious.

If desired, the gear or star wheels 413 and 413D may engage protrusions of any kind instead of or additionally to rollers 412. For example, the wheels 413 or 413D may engage extensions or hubs 412A or 412B, FIGURE 49, of the rollers 412. The wheels 413 or 413D would be moved axially the required amount.

The tray and cover raising mechanism 52

A tray and cover raising mechanism or means is provided for raising the trays 12 and covers 10 from the openings 134 of the orbital conveyor 38 into the cover and tray securing or wrapping mechanism 48 and thereafter delivering the covered trays as desired.

FIGURES 1-5, 23, 25, and 29 show this mechanism

A series of lifting platforms 482, FIGURE 23, are moved in unison with the orbital conveyor 38 by means of a pair of chain belts 484.

The lifting platforms 482 lift the trays 12 and covers 10 from the openings 134 in the conveyor 38 at the proper time to place the trays and covers within the tray and cover securing unit 410 properly to wrap the covers around the edges of the trays. The lifting platforms 482, the tray openings 134 and the sealing units 410 all travel rightward in unison so the action is a continuous one without the necessity of stopping the orbital conveyor 38 or the other chain conveyor of the machine.

The chain belts 484 which move the lifting platforms 482 ride on the stationary supporting bars 486, FIGURE 5, to prevent sagging of the chain belts 484 along the upper straight runs. The chain belts 484 pass over the sprocket pulleys 488 and 490, FIGURES 1 and 3. On the bottom or return runs of chain belts 484, the platforms 492, FIGURES 5 and 23, which carry this construction ride on stationary supporting bars 494 by means of the sliding members 496. The sprocket pulleys 488 and 490 are carried by shafts 498 and 500 respectively.

The platform 492 carries a supporting tube 502', FIGURE 23, in which the reciprocating rod 504 reciprocates. A compression spring 506 biases the rod 504 downward on the upper run by means of the nut 508 and combined set screw and guide 510, which reciprocates in slot 512.

The travel of the platforms 482 is coordinated with the travel of the orbital conveyor, so a lifting platform 482 is aligned with and travels with each tray opening 134 of the orbital conveyor 38.

At the proper time in the travel of the opening 134 and platform 482 the platform 482 is raised and lowered in a manner properly to feed a tray 12 and cover 10 into the securing mechanism 48 long enough for the securing or crimping operation and then the secured or crimped cover and tray are lowered slightly and then raised again in a manner so the cover and tray are properly deposited on the delivery means at right end of the machine.

To this end the roller 514, FIGURE 23, engages a series of stationary, longitudinal cam surfaces to produce the desired vertical movement of the platform 482. At the same time, another series of cam surfaces above the wrapping units 410 move a pressure plate 516 of the units 410 vertically to cooperate with the platform 482 to produce the proper vertical motion of the covers 10 and trays 12 and properly to hold the covers on the trays until they are crimped.

A stationary cam surface 518 on cam plate 519 is shown in FIGURE 1, which has started to raise roller 514 and platform 482. A stationary cam surface 520 on cam plate 521 is also shown in FIGURE 1 which cooperates with cam surface 518 to bring the platform 482 and pressure plate 516 in proper relationship, as shown in dotted lines in FIGURE 25 in readiness to raise the cover 10 and tray 12 from the opening 134 in the plates 136 and 137 of conveyor 38 and into the sealing unit 410.

Preferably, the pressure plate 516 is brought into engagement with the cover 10 by cam 520 of cam plate 521 while the tray 12 is resting on the plate 136 and 137 of the conveyor 38 and as the grasping fingers 308 and 310 are releasing the leading corners of the cover 10. The pressure plate 516 then firmly holds the cover on the tray as the roller 514 rides on the straight level surface 523 of the cam 519, FIGURES 1 and 3, to maintain the raising platform ready to raise the tray and cover off the plates 136 and 137.

The rising cam surface 522 of cam plate 521, FIGURES 3 and 20, then cooperates with the rising cam surface 524, FIGURE 3, of the cam plate 519 to raise the roller 514 and platform 482 to place the tray 12 and cover 10 and pressure plate 516 into the position shown in FIGURES 26 and 27 ready to perform the cover sealing operation, which is shown in completed condition in FIGURE 28.

The pressure plate 516 has downward flanges 526, FIGURES 26-28, with cut out corners 528 properly to receive the beads of the trays 12.

Movement of the pressure plate 516 is produced by roller 530, FIGURES 24 and 25, which is rotatably attached to horizontal pin 532, which in turn is attached to vertical pins 534, which are attached to pressure plate 516. The horizontal pin 532 has horizontal plates 536 which are attached to the vertical pins 534. The compression springs 538 surround the pins 534 and bias the pressure plate 516 upwardly. Upward movement is stopped by inward flange plates 539. Plate 516 is moved up and down when the cams 521 and 540, FIGURE 20, move the roller 530 of FIGURES 25 and 26 up and down.

Preferably, the cam 540 is made to move the pressure plate 516 down at the time when the die 48 is in fully closed position by the action of the closing cams 54 at positions 548, FIGURE 22. This produces a complete tuck around the bead of the tray, as shown in FIGURE 28. Another down cam 540A, FIGURES 3 and 22, for roller 530 may be used to knock any stuck tray and cover out of the die 48, when the die has been sufficiently opened by cams 54 near position 546, FIGURE 22.

25 *Means 54 to operate the cover and tray securing mechanism*

Means 54 are provided to cause the cover wrapping means 48 to wrap the covers 10 around the tops of trays or receptacles 12 while they are in the units 410.

FIGURES 5, 22, 24-28, 45-48 and 51 show the means for operating the cover and tray or receptacle securing units 410 of cover wrapping means 48 as units 410 travel along in a rightward direction, FIGURE 48, over the trays 12 and covers 10 which also travel rightwardly in synchronism with the units 410.

As the trays 12 and covers are moved rightwardly, FIGURE 48, and are raised into the securing units 410, the stationary cam means 54, FIGURE 22, causes the passing securing unit 410 to operate and wrap the cover 10 around the edges and corners of the tray 12.

The stationary cam means 54 may include two downwardly directed channel members 542 which are spread relatively far apart at their ends 544 and 546 and curve toward each other at their centers 548.

45 As the securing units 410 travel from left to right in FIGURE 22, under the stationary channels 542, the vertical rollers 480, FIGURES 24, 25 and 49, enter the ends 544 of the inverted channels 542, FIGURE 22. As the units 410 continue to move rightward under FIGURE 22, the vertical rollers 480, FIGURES 24 and 49, are pulled toward each other until the rollers 480 reach their closest dotted line positions 480A in FIGURE 49. At this time the rollers 480 are in the close central positions 548, FIGURE 22, of the inverted channels 542. At this time the cover wrapping operations in the units 410 have been performed, as more fully elsewhere described.

60 Further rightward movement of the units 410 causes the inverted channels 542 to spread apart the vertical rollers 480 to the full line positions 480 in FIGURE 49. This is caused by the passage of the rollers 480 into the spread apart outlets 546, FIGURE 22, of the inverted cams. This spreading action of the rollers releases the trays or receptacles and wrapped covers from the units 410, as elsewhere described, so the trays and wrapped covers may be then be carried by the lifting platforms 482 to the receiving track construction 56, elsewhere described.

65 The movements of vertical rollers 480 toward and away from each other cause corresponding movements of the links 470, FIGURES 24 and 49. The movements of the links 470 cause corresponding diagonal movements of the corner members 460, 456 and 454 toward and away from the central part of the unit 410, as indicated by the dotted lines 460A in FIGURE 49 and 75 in full lines on the left side of FIGURE 24.

Inward diagonal movement of the corner members 460, 456 and 454 cause the covers 10 to be wrapped around the edges of the trays 12 by movements shown in FIGURES 24-28 and elsewhere described. Outward diagonal movement of the corner members 460, 456 and 454 causes reverse releasing movements of the trays and wrapped covers, as is obvious.

The inward movement of the corner members 460, 456 and 454 also causes the inward rocking of the wrapping rollers 436 (and 438) from the position of FIGURE 27 to the complete wrapping position of FIGURE 28.

Each corner plate 456, FIGURES 24, 25, 26 and 45, carries a pair of vertical rollers 572 and 574 which engage respectively the wrapping rollers 436 and 438. By 15 comparing the right sides of FIGURES 24 and 25 with the left side, it will be seen that the vertical rollers 572 have moved from the outward positions on the right sides of FIGURES 24 and 25 and in FIGURE 45, to the inward positions on the left sides of FIGURES 20 24 and 25. The vertical rollers 572 on the right side cause the horizontal wrapping rollers 436 to be in the outward position corresponding to FIGURES 27 and 45. The vertical rollers 572 on the left sides of FIGURES 24 and 25 move the horizontal rollers 436 to the inward position corresponding to FIGURE 28.

The vertical rollers 574 at the upper and lower edges of FIGURE 24 produce the same action on the horizontal rollers 438. The right side position of FIGURE 24 shows the vertical rollers 574 and horizontal rollers 438 in the outer positions while the left side of FIGURES 25 24 and 25 shows them on the inner position.

The stationary tray and cover receiving track construction 56

FIGURES 3 and 29-32 show this track construction 56. A track construction 56 includes two pairs of wire-like tracks 576 and 578 which are tied together by transverse members 580. The track 56 may be supported by any suitable means such as by brackets 582 which may be carried by any suitable part of the frame work.

The track construction 56 receives the covered trays, such as 12A, FIGURE 29, as it is being carried by the platform 482 after the tray has been deposited from the wrapping mechanism 48.

In FIGURE 3 the top level surface 525 of stationary cam 519 causes the rollers 514, which move the platforms 482 vertically, to move the platforms 482 to their highest position within the wrapping unit 410, as shown in FIGURE 28. At that time the down cam 540, FIGURE 3, gives the pressure plate 516 a down push through roller 530, FIGURES 24 and 25, to wrap the cover edge 448, FIGURE 28, completely around the bead of the tray.

Thereafter the roller 514 which actuates the platform 482 is lowered along slanting surface 584, FIGURE 3, and is then raised along slant 586 and level run 587 to raise the tray on to the track 576, FIGURES 3 and 29.

The tray is lowered by slanting surface 584, FIGURE 3, to permit the next succeeding die or securing unit 410 to clear the tray 12 without knocking the tray off the platform 482.

The trays 12 and wrapped covers 10 are removed from the wrapping units 410 mostly by the upward movement of the units 410 as their rollers 412 enter the grooves 425 and 427 at the right end of FIGURE 48. This constitutes means for removing the trays and covers from the units. The cam 540A, FIGURE 3, knocks out any trays which might stick in the units 410.

The downward limit of movement of roller 514, FIGURES 3 and 23, may be made sufficiently high by the action of pin 510 in FIGURE 23 so the roller 514 clears the shaft 500 in FIGURE 3, and also the corresponding shaft 498 in FIGURE 1. Alternately or additionally,

5 a stationary guide means, not shown, may surround these shafts 498 and 500 to guide the rollers 514 around these shafts.

The tray and cover pushing mechanism 58

The track construction 56 and the pushing mechanism 58 constitute means for removing the wrapped covers and trays or receptacles from the units 410.

FIGURES 3, 29 and 30 show the moving or pushing mechanism 58.

Two chain belts 590 pass over sprocket pulleys 592 and 594, which are fixed on shafts 590B and 590A respectively. The straight runs of the belts 590 are supported by the support bars 596 and 598. Bars 598 are adjusted by brackets 148A and side plates 152A which are similar respectively to brackets 148 and side plates 152 of FIGURES 6, 7, 9 and 10. The belts 140 and 590 are similar in substantially all respects. The belts carry a plurality of fingers 600 which push the covered trays 12A along the track 56, in a manner similar to fingers 138.

The chain belts 590 are driven from shaft 186A by chain belt 602 which passes over sprocket wheel 604 which is fixed on shaft 186A. The belt 602 also passes over idler sprocket wheel 606 on idler shaft 607. Belt 602 drives sprocket wheel 610, which is secured to shaft 590B which drives the chain belts 590 by sprocket wheel 592.

30 The action of belts 590 and fingers 600 is the same as that of belts 140 and fingers 138 in FIGURES 6, 7 9 and 10, including support bars 146, 156, etc.

If desired, a tray and cover receiving and discharging belt construction 60, FIGURES 3 and 29, may be provided for receiving the trays 12 and covers 10 from the track construction 58. This belt construction 60 may carry the covered trays or receptacles to suitable packing tables or the like. It may have its own motor drive, not shown.

35 Chain belts are used wherever it is necessary to maintain the parts in synchronized operation. All of these chain belts are directly or indirectly connected with the main motor 192. If indirectly connected, then the indirect connection is a positive drive such as by one or more other chain belts, sprockets, gears, etc. Substantially all of these drives are shown in FIGURES 55 and 56.

The number of cover wrapping or securing units 410 which are mounted on the mechanism is sufficient so 50 there is one unit 410 for each opening 134 of conveyor 58. For example, in the relative size shown in the drawings there may be six units 410 on the mechanism 48. Every opening 134 should receive a tray 12 on the rightward movement of conveyor 38. If there is a tray missing in one of the openings 134, the tray sensing unit 40, 55 42 will stop the feeding of a cover for the missing tray. The failure to deliver the cover causes the cover sensing device to stop the machine.

The invention may be practiced with or without some 60 of the automatic features or other features disclosed depending on the extent of use desired of the various advantages available to the user.

In operation, trays or receptacles 12, with food or the like in them, and placed either directly on the belts 62 or on a belt conveyor which feeds the trays on to belts 62. The trays move rightwardly (as seen in the figures) on these belts 62 until the leading tray 12A is arrested by plate or barrier 84, FIGURE 6. At the proper time the plate 84 drops down and the plate 85 pushes up. This releases the leading tray or receptacle 70 12A to travel rightward on to the track 28, FIGURES 6, 7, 9 and 10. Thereafter the barriers or plates 84 and 86 change to their original positions and the tray 12B, FIGURE 6, then advances to take the position originally held by tray 12A.

The tray 12A is deposited on the track 28 between the downwardly directed pushing fingers 138 which push the tray along the tracks 28 and 29 at the proper speed. The tray reaches the various positions shown in FIGURES 11 and 12 where the tray is first pushed over the roller 164 and inside one of the openings 134 of the plates 136 and 137 of the conveyor 38. The roller 164 maintains the tray at the higher level 12C. As the tray moves rightward, the rollers 164 and 166 rotate so the aligned sides 168 of these rollers are at their top position when the tray 12C starts to move on to the the roller 166. Continued movement of the tray rightward is produced by the holding means or opening 134 of plates 136 and 137. When the tray is substantially over the roller 166, the low part 166A of roller 166 is in the up position as shown in cross section in FIGURE 12, so the tray has been lowered to the level of position 12D and is ready to ride with its rim 22 resting on the plates 136 and 137.

If there happens to be a tray lacking in any one of the conveyor tray openings 134, then the empty opening passes between the wave energy couple 40, 42, FIGURE 13. The passage of wave energy between the couple 40, 42 and through the empty tray opening 134 causes the solenoid 244 to push down on rod 246. This triggers the one revolution clutch by movement of lever 240 to declutching position, so the cover feeding mechanism 44 is not actuated at pulley 228. This causes the cover feeding mechanism 44 not to deliver a cover 10 which otherwise would have been delivered for the tray which should have been in the empty opening 134. This indirectly stops the machine, as the absence of the cover in another mechanism reacts to stop the machine.

However, if the operation continues without this interruption or is resumed after proper correction, then the tray arrives under the cover feeder trough 250 of FIGURES 1, 15, 16, and 38-41.

The cover feeder mechanism 44, FIGURE 1, cuts sheet covers of proper length and width from the sheet roll 260 and delivers the cut covers vertically at 10A, FIGURES 1 and 38, into the trough 250 at the proper time to supply a tray which is passing under the trough 250. A gate 256, FIGURES 38-41, is in down, full line, position to arrest a previously released cover 12B until the proper moment of travel of the tray.

At the proper moment, the gate 256 is raised to upper dotted line position, FIGURE 38. At this instant fingers 310 and 308, of FIGURES 38 and 17-19 reach the position of dotted line finger 310 in FIGURE 38. The fingers 308 and 310 then grasp the corners 303 of the cover 10B and pull the cover along, as indicated by the arrows 348, FIGURE 18, rightward directly over a tray 12, which is being carried rightward by an opening 134 of conveyor 38. The cover and tray or receptacle are shown in FIGURE 33.

The fingers 308 and 310 are moved in adjacent horizontal orbits 346 as shown in dotted lines 346 in FIGURE 18. The fingers have been spread apart as they travelled the arc 318 at the left end of FIGURE 18. At the radius 322 the lower finger was released by reaching the end 319 of wire cam 330 which permitted the short end 316 to snap down and the long end 317, FIGURE 44, to snap up. The cams 330 and 335, FIGURE 18 cause the fingers 308 and 310 to grasp the covers 10 near the left end of FIGURE 18 and to release the covers near the right end of FIGURE 18.

The covers 10 and trays 12 have now reached the position slightly to the right and under shaft 403 of FIGURE 1 where a lifting platform 482 is about to rise and lift the tray and cover by the upward action of platform 482. At the same time pressure plate 516, FIGURE 25, of wrapping unit 410 has been pushed down by roller 530 to the dotted line position of FIGURE 25. The grasping fingers 308 and 310 release the cover 10 at this time. The pressure plate holds the cover 10 on the tray

12 as the elevating platform 482 starts to raise the tray and cover into the unit 410.

When the tray, cover and pressure plate have been raised to the full line position of the right side of FIGURE 25, the unit 410 is operated by cam construction 54 of FIGURE 22 to wrap the cover 10 around the tray as shown on the left side of FIGURE 25. This is accomplished by the inward movement of rollers 480 which buckle or fold the links 470 from the straight alignment on the right side of FIGURE 24 to the buckled condition on the left side of FIGURE 24. This moves the corner wrapping means 453, FIGURES 24 and 45 diagonally inward to wrap the corners of the cover 10. The corner wrapping means 453 also rocks the wrapping rollers 436 and 438 to wrap the sides of the cover 10 around the tray or receptacle 12.

Thereafter the rollers 436 and 438 and the corner wrapping means are returned to open position by the opening or spreading action cam means 542 of FIGURE 22, which spreads apart the rollers 480 of the unit 410, FIGURES 24 and 25.

The units 410 are moved in a vertical orbit by the chain construction 408, FIGURE 48. The units 410 are maintained with the same face down throughout the orbit by the passage of the rollers 412 of the units 410 up and down the curved grooves 425 and 427, FIGURE 48, while the centers of the units 410 are moved by the pin-like members 434 and sprocket wheels 406 along curves 406A, FIGURE 48, "parallel" to the curves 425 and 427.

The units 410 are maintained horizontal in straight upper and lower runs by bars 414, 416, 418 and 420 which hold the rollers 412 and the pin-like members 434 in horizontal positions as they travel laterally along these runs.

If desired, the star or sprocket wheels 413 and/or 413D of FIGURES 49, 50, 53 and 54 may be added at the location of curved grooves 425 and/or 427, as shown in FIGURES 49, 50, 53 and 54.

After the cover 10 has been wrapped in the unit 410, the unit 410 rises along the right end of FIGURE 48 leaving the tray and wrapped cover resting on the platform 482, FIGURE 48.

The platform 482 delivers the tray and wrapped cover 12A, FIGURE 29, on the stationary receiving track 56, FIGURES 29-31, which delivers them to a delivery conveyor 60 or the like for conveyance to a zone for freezing the food or for other use.

Thus apparatus and method have been provided in which a series of substantially horizontal trays or receptacles 12 are moved laterally. A series of corresponding horizontal covers 10 are moved over the trays or receptacles 12. A series of wrapping units 410 are moved above said laterally moving trays or receptacles and covers. Pressure plates 516 then hold the covers 10 on the trays or receptacles 12 while the elevating platforms 482 raise the trays or receptacles and covers 10 into the wrapping units 410. The units 410 are operated to wrap the covers 10 around the trays or receptacles 12 while the trays or receptacles and covers are in the units 410 and while they are moving laterally.

60 This permits an efficient and unhurried wrapping action in the units 410 and provides an efficient tray or receptacle and cover feeding action into the units 410 and an efficient tray or receptacle and wrapped cover delivery from the units 410.

65 It is thus to be seen that very effective and efficient apparatus and method have been provided for wrapping covers over trays or receptacles and the like in large quantities and in high quality condition.

70 While the form of the invention now preferred has been disclosed as required by statute, other forms may be used, all coming within the scope of the claims.

75 What is claimed is:

1. Apparatus for placing and wrapping sheet covers over the edges of trays comprising: an automatic tray feeding, arresting and regulated releasing belt construc-

tion; a stationary track construction receiving and supporting trays from said belt construction; tray moving mechanism for moving trays along said track; a tray lowering construction receiving trays from said track at one level and lowering said trays to a lower level; an orbital tray supporting conveyor having a horizontal orbital axis and an upper horizontal tray supporting conveyor run and receiving trays from said lowering construction at said lower level and conveying said trays in a series along said horizontal tray supporting run; tray absence sensing means sensing the absence of a tray from its normal place in said orbital conveyor and controlling said apparatus in response to said absence; a cover and tray wrapping mechanism including a cover wrapping unit carrying conveyor carrying a plurality of cover wrapping units orbitally along a horizontal cover wrapping run parallel to and above said horizontal tray supporting conveyor run; sheet cover feeding means feeding sheet covers over said trays and tray supporting conveyor at the rate of one cover for each tray carried by said conveyor in advance of said cover wrapping run; sheet cover holding and moving means independent of said trays moving said sheet covers over and along with each respective tray on said tray supporting conveyor from said sheet cover feeding means to a cover raising position under said wrapping mechanism; cover absence sensing mechanism sensing the absence of a cover from its normal place over one of said trays and said conveyor and controlling said apparatus in response to said absence; tray and cover raising mechanism which raises said trays and covers from said orbital conveyor into said cover and tray wrapping mechanism; means to operate said cover and tray wrapping mechanism while each of said respective covers and trays are raised into said wrapping mechanism; a stationary tray and wrapped cover receiving track receiving said trays and wrapped covers from said wrapping mechanism; and a tray and wrapped cover moving or pushing mechanism for moving or pushing said trays and wrapped covers along said receiving track.

2. Apparatus for placing and wrapping sheet covers over the edges of trays; a tray supporting horizontal rotation axis orbital conveyor; a plurality of spaced tray holding means on said conveyor to receive trays fed thereon; sheet cover feeding means feeding sheet covers over said trays and orbital conveyor at the rate of one cover for each tray carried by said conveyor; a cover and tray wrapping mechanism over said orbital conveyor; sheet cover moving means independent of said trays moving said sheet covers over and along with each respective tray on said orbital conveyor from said sheet cover feeding means to a raising position under said cover and tray wrapping mechanism; tray and cover raising mechanism which raises said trays and covers from said orbital conveyor into said cover and tray wrapping mechanism; means causing said sheet cover moving means to release said covers to permit said raising mechanism to raise said trays and covers from said orbital conveyor; means to operate said cover and tray wrapping mechanism while each of said respective covers and trays are raised into said wrapping mechanism; and means releasing said covers and trays in cover wrapped condition from said wrapping mechanism.

3. Apparatus for placing and wrapping sheet covers over the edges of trays comprising: an automatic tray feeding, arresting and regulatedly releasing belt construction; a stationary track construction receiving and supporting trays from said belt construction; tray moving mechanism for moving trays along said track; a tray lowering construction receiving trays from said track at one level and lowering said trays to a lower level; a horizontal rotation axis tray supporting orbital conveyor receiving trays from said lowering construction at said lower level and conveying said trays in a series along said conveyor; sheet cover feeding means feeding sheet covers over said trays and orbital conveyor at the rate of

one cover for each tray carried by said conveyor; a cover and tray wrapping mechanism over said orbital conveyor; sheet cover moving means independent of said trays moving said sheet covers over and along with each respective tray on said orbital conveyor from said sheet cover feeding means to a raising position under said cover and tray wrapping mechanism; tray and cover raising mechanism which raises said trays and covers from said orbital conveyor into said cover and tray wrapping mechanism; means causing said sheet cover moving means to release said covers to permit said raising mechanism to raise said trays and covers from said orbital conveyor; means to operate said cover and tray securing mechanism while each of said respective covers and trays are raised into said wrapping mechanism; and means releasing said covers and trays in cover wrapped condition from said wrapping mechanism.

4. Apparatus comprising: a movable orbital conveyor with receptacle holding means; means automatically to feed receptacles into said holding means; and automatically to feed sheet covers over said receptacles; cover carrying means independent of said receptacles to carry said covers along over said receptacles while said receptacles are being moved by said conveyor; cover wrapping means above said conveyor; means to cause said cover carrying means to release said covers under said cover wrapping means; means to raise said receptacles and covers to said cover wrapping means; and means to cause said wrapping means to wrap said covers around the edges of said receptacles.

5. Apparatus comprising: a movable orbital conveyor with receptacle holding means and movable along a first named relatively long horizontal run; means automatically to feed receptacles into said holding means; means automatically to feed sheet covers over said receptacles; means to carry said covers along over said receptacles while said receptacles are being moved by said conveyor; cover wrapping means above said conveyor carried by a second movable orbital conveyor and movable along a second named relatively long horizontal run above said first named horizontal run; means to raise said receptacles and covers to said wrapping means; and means to cause said wrapping means to wrap said covers around the edges of said receptacles.

6. Apparatus comprising: a movable orbital conveyor movable about a first named orbit with a relatively long straight first named run, said conveyor having receptacle holding means movable along said run, said holding means receiving receptacles with covers over them for movement along said run; a receptacle and cover wrapping unit moving orbital conveyor construction movable about a second named orbit and having a relatively long straight second named run substantially parallel to said first named run; a plurality of receptacle and cover wrapping units moved by said unit moving orbital conveyor in said second named orbit in synchronism with said receptacles and covers in said straight runs; means for causing relative movement between said receptacles with covers and said wrapping units to place said receptacles and covers in said units; means for operating said wrapping units to wrap said covers around said receptacles while said receptacles and covers are in said units; and means for removing said receptacles with covers wrapped around them from said wrapping units.

7. Apparatus according to claim 6 in which said receptacle and cover wrapping units remain with their sides facing the same direction as said units are moved throughout the orbit of said wrapping unit moving orbital construction.

8. Apparatus according to claim 6 in which said orbits are vertical, and said runs are substantially horizontal.

9. Apparatus according to claim 8 in which said units are maintained with their same side down during their travel in said second named orbit.

10. Apparatus comprising: a first named orbital conveyor movable about a first named orbit with a relatively long straight first named run; receptacle holding means on said conveyor to receive receptacles and transport them substantially along said first named run; means to feed receptacles on said tray holding means; means to feed covers on said receptacles; a second named orbital conveyor movable about a second named orbit with a relatively long straight second named run parallel to said first named run; a plurality of receptacle and cover wrapping units carried by said second named orbital conveyor around said second named orbit and along said second named run adjacent to and in synchronism with said receptacle holding means; means for causing relative movement between said receptacles and cover and said wrapping units; means to operate said units to wrap said covers around said receptacles; and means to remove said receptacles and wrapped covers from said units.

11. Apparatus comprising: a substantially horizontal stationary track construction having two aligned sections with a gap between them; means for moving receptacles along said sections and past said gap; and an orbital conveyor having a plurality of plates with receptacle holding means, said conveyor moving said plates under one section, through said gap and over the other section.

12. Apparatus comprising: a substantially horizontal stationary track construction having two aligned sections with a gap between them; means for moving receptacles along said sections and past said gap; an orbital conveyor having a plurality of plates with receptacle holding means, said conveyor moving said plates under one section, through said gap and over the other section; and means to cause said receptacles to be delivered from said second section into said receptacle holding means.

13. Apparatus comprising: two longitudinally disposed substantially horizontal receptacle supporting smooth sided rolls with their ends adjacent each other and with first named portions of their sides aligned with each other and with second named portions of their sides misaligned; means to rotate said rolls; and means to feed receptacles longitudinally along said rolls to rest simultaneously on said first named portions at a relatively high level and to rest on one of said second named portions at a relatively low level.

14. Apparatus comprising: a movable conveyor having a series of receptacle holding means to receive one receptacle for each holding means; a cover feeding means to feed covers at the rate of one cover for each receptacle; cover moving means for moving said covers over respective receptacles; and cover absence sensitive means electrically sensitive to the absence of an electrically conductive cover in said cover moving means for modifying said apparatus.

15. Apparatus according to claim 14 in which said cover moving means is a series of grasping fingers to grasp covers fed by said cover feeding means, and in which said cover absence sensitive means include electric contactors carried by said fingers to contact different places on said covers when grasped; and an electric circuit sensitive to the failure of the flow of the electric current between said electric contactors because of the absence of said conductive cover between said fingers.

16. Apparatus comprising: a movable conveyor having a series of receptacle holding means to receive one receptacle for each holding means and movable in a relatively long horizontal path; a cover feeding means to feed covers at the rate of one cover for each receptacle; cover moving means independent of said receptacles for moving said covers over respective receptacles as said receptacles move along said horizontal receptacle path; receptacle and cover wrapping units movable in a relatively long horizontal unit path above said receptacle path for wrapping said covers around said receptacles; means for serially and vertically moving said receptacles and covers into said wrapping units; and means to operate said wrapping units

to wrap said covers around said receptacles in said units while said wrapping units travel in said relatively long horizontal unit path.

17. Apparatus comprising: a first named orbital conveyor movable about a first named straight run; receptacle holding means on said conveyor to receive and transport receptacles along a first named straight run of said orbit; cover feed means to feed covers over said receptacles; a second named orbital conveyor movable about a second named straight run adjacent said first named straight run; receptacle and cover wrapping units moved by said second named conveyor past said second named straight run; a third orbital conveyor movable about a third named orbit adjacent said first named orbit; receptacle and cover moving means carried by said third conveyor and moving receptacles and covers into said units while said units pass said second named straight run; and operating means to operate said units to wrap said covers around said receptacles in said units.

18. Apparatus according to claim 17 in which said orbits are vertical.

19. Apparatus according to claim 17 in which said receptacle holding means in said first named orbital conveyor are openings in said first named orbital conveyor and in which said receptacle and cover moving means are platforms which pass through said openings and which lift said receptacles and covers into said units.

20. Apparatus comprising a first named orbital conveyor movable about a first named orbit with a straight first named run; receptacle holding means on said conveyor to receive receptacles with covers on them for movement along said first named run; a second named orbital conveyor movable about a second named orbit with a second straight run adjacent and parallel to said first named run; receptacle and cover wrapping units moved by said second named conveyor around said second named orbit and along said second named run; means to cause relative movement between said receptacles with covers and said wrapping units; and operating means to cause said units to wrap said covers around said receptacles while said covers and receptacles are in said units.

21. Apparatus according to claim 20 in which said second named conveyor includes a belt construction movable around wheel constructions adjacent both ends of said second named run.

22. Apparatus according to claim 21 in which said units include guiding protrusions at opposite ends of said units and in which arcuate guiding means for said guiding protrusions are provided on opposite sides of said wheels to maintain said units facing in the same direction while moving throughout said second named orbit.

23. Apparatus according to claim 22 in which one of said arcuate guiding means includes a star wheel construction which is engaged by a guiding protrusion on each of said respective units.

24. Apparatus comprising: a movable first conveyor having a straight first run for moving a receptacle and cover past a cover wrapping zone; and a movable second conveyor having a second run; a receptacle and cover wrapping unit moved by said second conveyor and movable adjacent said receptacle and cover and including a generally rectangular main plate; side cover wrapping rollers and front and rear cover wrapping rollers rockable under said main plate; corner cover wrapping members movable diagonally toward the center of said plate and having means to wrap the corners of said cover and having means to rock said side, front and rear rollers; means to move said cover and receptacle into said unit and means to move said corner cover wrapping members inwardly and outwardly.

25. Apparatus according to claim 24 in which two pairs of links are attached to said corner cover wrapping members and respectively to two spaced pin constructions above said main plate, and in which downwardly directed

cam constructions engage said pin constructions to move said corner cover wrapping members.

26. Apparatus according to claim 24 in which a pressure plate under the main plate is movable to engage and hold said cover on said receptacle while said cover and receptacle are being moved into said unit.

27. Apparatus according to claim 26 in which said pressure plate is moved by a roller above said main plate and cam means to engage said roller to move said pressure plate.

28. Apparatus comprising: a generally rectangular cover wrapping main plate; side cover wrapping rollers and front and rear cover wrapping rollers rockable under said main plate; corner cover wrapping members movable diagonally toward the center of said plate and having means to wrap the corners of the cover and having means to rock said side, front and rear rollers; and means to move said corner cover wrapping members inwardly and outwardly.

29. Apparatus comprising: means for laterally moving a series of horizontal receptacles; cover moving means independent of said receptacles for laterally moving a series of corresponding horizontal covers over said receptacles; means for moving a series of wrapping units above said laterally moving receptacles and covers; release means to cause said cover moving means to release said covers under said wrapping units; means to hold said covers on said receptacles under said units after said covers have been released by said cover moving means; means to raise said receptacles and covers into said units while moving laterally; and means to operate said units to wrap said covers around said receptacles while said receptacles and covers are in said units and moving laterally.

30. A method comprising: laterally moving a series of horizontal receptacles substantially horizontally in a relatively long horizontal receptacle path; moving a series of corresponding horizontal covers in a relatively long horizontal cover path independently of said receptacles and over said receptacles; moving a series of cover and receptacle wrapping units above said laterally moving receptacles and covers in a relatively long horizontal unit path; holding said covers on said receptacles under said units; raising said receptacles and covers into said units while said receptacles, covers and wrapping units are moving laterally; and operating said units to wrap said covers around said receptacles while said receptacles and covers are in said units and are moving laterally along said horizontal unit path.

31. Apparatus comprising: a conveyor with receptacle holding means laterally to move a series of horizontal receptacles; grasping means independent of said receptacles for laterally moving a series of corresponding horizontal covers over said receptacles; a conveyor with a series of wrapping units for moving said series of units above said laterally moving receptacles and covers; release means to cause said cover grasping means to release said covers on said wrapping units; pressure plates to hold said covers on said receptacles under said units after said covers have been released by said cover grasping means; elevating platforms to raise said receptacles and covers into said units while said receptacles and covers are moving laterally; and means to operate said units to wrap said covers around said receptacles while said covers and receptacles are in said units and moving laterally.

32. Apparatus comprising: a movable orbital first conveyor construction having a series of receptacle holding means to move horizontal receptacles laterally; a second orbital conveyor construction having a series of grasping means independent of said receptacle to grasp corresponding horizontal covers and to move said covers laterally over said receptacles; a third orbital conveyor construction with a series of wrapping units to move said units above said laterally moving receptacles and covers; release means to cause grasping means to release said cover

under said wrapping units; pressure plates to hold said covers on said receptacles under said units after said covers have been released by said grasping means; elevating platforms to elevate said receptacles and covers into said units; and means to operate said units to wrap said covers around said receptacles while said receptacles and covers are moving laterally.

33. Apparatus comprising: a movable orbital first conveyor construction having a series of receptacle holding means to move horizontal receptacles laterally; a second orbital conveyor construction having a series of grasping means independent of said receptacles to grasp corresponding horizontal covers and to move said covers laterally over said receptacles; a third orbital conveyor construction with a series of wrapping units to move said units above said laterally moving receptacles and covers; release means to cause said grasping means to release said covers under said wrapping units; pressure plates to hold said covers on said receptacles under said units after said covers have been released by said grasping means; elevating platforms to elevate said receptacles and covers into said units; means to operate said units to wrap said covers around said receptacles while said receptacles and covers are moving laterally; said second orbital conveyor construction including a pair of horizontal orbital conveyors on each side said first conveyor construction and carrying cover grasping fingers to move said covers laterally over said receptacles.

34. Apparatus comprising: a movable vertical orbital first conveyor movable about a first named vertical orbit with a relatively long upper straight horizontal first named run, said conveyor having receptacle holding means movable along said run, said holding means receiving receptacles with covers over them for movement along said run; a receptacle and cover wrapping unit moving vertical orbital second conveyor movable about a second named vertical orbit above said first named orbit and having a relatively long lower straight horizontal second named run substantially parallel to said first named run; a plurality of receptacle and cover wrapping units moved by said second conveyor in said second named vertical orbit and along said second named run, said wrapping units being moved by connection means with said second conveyor and being held continuously facing downwardly by guiding protrusions extending from said units into guiding groove means; means for causing relative movement between said receptacles with covers and said wrapping units to place said receptacles and covers in said units; means for operating said wrapping units to wrap said covers around said receptacles while said receptacles and covers are in said units; and means for removing said receptacles with covers wrapped around them from said wrapping units.

35. Apparatus according to claim 34 with vertically movable platforms movable through openings forming said holding means in said first conveyor to push said receptacles and covers upwardly into said wrapping units.

36. Apparatus comprising: a substantially horizontal stationary track construction having first and second substantially aligned sections with a gap between them; means for moving receptacles along said first section, past said gap and along said second section in a relatively elevated condition; an orbital conveyor having a plurality of receptacle holding openings, said conveyor moving said openings under said first section through said gap and over said second section; and receptacle lowering means to receive said receptacles in said relatively elevated condition from said second section and to lower said receptacles to a relatively lowered condition into said holding openings.

37. An apparatus according to claim 33 with said receptacle lowering means having two longitudinally disposed substantially horizontal receptacle supporting smooth sided rolls adjacent the discharge end of said second section with their ends adjacent each other and

with first named portions of their sides aligned with each other and with said second section to receive said receptacles from said second section in said relatively elevated condition and with second named portions of their sides misaligned; means to rotate said rolls; and means to move said receptacles longitudinally along said rolls to rest simultaneously on said first named portions at said relatively elevated condition and to be lowered in said holding openings while resting on one of said second named portions in said relatively lowered condition.

38. Apparatus for placing and wrapping sheet covers over the top edges of receptacles comprising: an orbital receptacle supporting frictional conveyor having a horizontal rotational axis and an upper horizontal receptacle supporting frictional run; upward receptacle edge limit parallel angle beams above said frictional run; two arresting barriers alternately movable up and down along said frictional run serially to arrest and release said receptacles as needed; a horizontal stationary track construction receiving and supporting receptacles from said frictional conveyor; a horizontal rotational axis orbital receptacle pushing conveyor having a lower horizontal receptacle pushing run above said stationary track construction and having downwardly directed receptacle pushing fingers moved along said track construction; a pair of parallel horizontal receptacle receiving rolls extending longitudinally along said stationary track and rotatable concentrically on a pair of parallel horizontal shafts; a pair of parallel horizontal receptacle lowering rolls adjacent said receptacle receiving rolls and rotatable eccentrically on said horizontal shafts; a horizontal rotational axis orbital receptacle moving and holding conveyor having an upper horizontal holding conveyor straight run and having receptacle holding openings receiving receptacles from said receptacle lowering rolls; a horizontal rotational axis orbital cover wrapping unit conveyor carrying a plurality of continuously downwardly facing cover wrapping units along a horizontal cover wrapping straight run parallel to and above said horizontal supporting conveyor straight run with said wrapping units moving above said openings in said holding conveyor; sheet cover feeding means feeding sheet covers over receptacles in said holding openings at the rate of one cover for each receptacle in advance of said cover wrapping run; two vertical rotational axis orbital sheet cover holding and moving conveyors respectively on each side of said receptacle holding and moving conveyor and having horizontal cover grasping fingers grasping said sheet covers as fed from said feeding means and moving said covers over and along with each receptacle to a cover and receptacle raising position under said wrapping unit conveyor; a horizontal rotational axis orbital receptacle and cover raising conveyor within said holding conveyor and having a plurality of receptacle lifting platforms moved in unison with said openings in said holding conveyor as they pass along said cover wrapping zone; means to lift said platforms to lift said receptacles and covers into said wrapping units at a proper wrapping sequence; means causing said grasping fingers to release said covers to permit them to be lifted into said wrapping units; means to operate said wrapping units when said receptacles and covers have been lifted into said wrapping units to wrap said covers over the edges of said receptacles and then to release said receptacles with covers wrapped over said edges; means to lower said platforms to lower said receptacles with wrapped covers from said wrapping units; a second horizontal stationary track construction receiving receptacles with wrapped covers; and a second horizontal rotational axis orbital receptacle pushing conveyor having a lower horizontal receptacle pushing run above said second stationary track construction and having downwardly directed receptacle pushing fin-

gers moved along said second stationary track construction.

39. Apparatus according to claim 38 with said receptacle moving and holding conveyor having a plurality of 5 pairs of plates each pivotally mounted on a pair of orbital chains and each plate having a notched edge facing a notched edge of the other plate to form a receptacle forming opening, and stationary bars along said upper horizontal holding conveyor run to hold said plates in horizontal position.

40. Apparatus according to claim 38 with said wrapping units each being centrally pivoted at both sides respectively to orbital chains which move in horizontal rotational axes on opposite sides of said units, and with 15 said units having guiding protrusions at their forward and back corners which ride between horizontal bars along straight runs of said wrapping unit conveyor and between curved grooves at the ends of said wrapping unit conveyor to maintain said wrapping units facing continuously downward.

41. Apparatus for placing and wrapping sheet covers over the top edges of receptacles comprising: a horizontal rotational axis orbital receptacle moving and holding conveyor having an upper horizontal holding conveyor straight run and having receptacle holding openings; a horizontal rotational axis orbital cover wrapping unit conveyor carrying a plurality of continuously downwardly facing cover wrapping units along a horizontal cover wrapping straight run parallel to and above said 25 horizontal holding conveyor straight run with said wrapping units moving above said openings in said holding conveyor; means to feed receptacles into said openings in advance of said wrapping straight run; sheet cover feeding means feeding sheet covers over said receptacles; two 30 vertical rotational axis orbital sheet cover holding and moving conveyors respectively on each side of said receptacle holding and moving conveyor and having horizontal cover grasping fingers grasping said sheet covers as fed from said feeding means and moving said covers over 35 and along with each receptacle to a cover and receptacle raising position under said wrapping unit conveyor; a horizontal rotational axis orbital receptacle and cover raising conveyor within said holding conveyor and having a plurality of receptacle lifting platforms moved in 40 unison with and through said openings in said holding conveyor as they pass along said cover wrapping zone; means to cause said platforms to lift said receptacles and covers into said wrapping units at a proper wrapping sequence; means causing said grasping fingers to 45 release said covers to permit them to be lifted into said wrapping units; means to operate said wrapping units when said receptacles and covers have been lifted into said wrapping units to wrap covers over the edges of 50 said receptacles and then to release said receptacles with covers wrapped over said edges; means to lower said platforms to lower said receptacles with wrapped covers from said wrapping units; and means to remove said receptacles with wrapped covers from said platforms.
